MULTIPLYING MACHINES CONTROLLED BY STATISTICAL RECORD CARDS

Eric John Guttridge, Barnes, John Harold Lucas, Caterham, and Ronald Percy Bawden Yandell, Streatham, London, England, assignors to Powers-Samas Accounting Machines Limited, London, England, a British company

Application March 31, 1953, Serial No. 346,054

Claims priority, application Great Britain
November 1, 1952

54 Claims. (Cl. 235—61.6)

This invention relates to calculating machines controlled by statistical record cards and in particular to an electrical calculating machine arranged to effect calculations from factors sensed from record cards.

It is one object of the present invention to provide for a calculating machine apparatus for effecting calculations electrically by the use of Eccles-Jordan trigger circuits as counters and registers and coincidence gates to control the entry of factors to the apparatus.

According to the present invention there is provided in an electrical calculating machine controlled by statistical record cards, calculating apparatus comprising a non-counting register, a first counting register, a second counting register to act as a result register, each said register including a plurality of denominational orders each including at least one binary counter by which a digit is registered, gating means connecting the registers to control the transfer of an amount entered in one register to at least one of the other two registers, a programme unit co-operating with the registers and gating means to determine the order of entry of amounts into the registers, recording means to record the result registered in the second counting register, and read-out means co-operating with the second counting register to transmit digit-representing pulses to the recording means to set up therein a record of the result read out from the second counting register.

Apparatus according to the present invention may be arranged to effect multiplication by repeated addition and when so arranged may include cycling selector gates to control the entry of an amount stored in the non-counting register to the first counting register, transfer gates to control the entry of an amount stored in the first counting register to the non-counting register after resetting thereof, and a transmit gate and a multiplier digit selector to control the entry of an amount stored in the non-counting register to the second counting register, the multiplicand entered into said first counting register being, during successive groups of five addition periods each, successively increased by powers of ten to a predetermined power, said transfer gates after each of the first two periods only of each said group transferring to the non-counting register the amount stored in the first counting register, the cycling selector gates during each of said five periods controlling the entry into the first counting register of the amount stored in the non-counting register, and the transmit gate and multiplier digit selector determining during which of the five periods of a group the amount stored in the non-counting register is transmitted to the second counting register. When a multiplicand consisting of an amount of mixed notation, for example a sterling multiplicand, is to be multiplied by a decimal multiplier containing a decimal fraction a decimal point selector is provided to determine the number of significant digits to the right of the decimal point, such selector comprising for each column of a card field to be sensed, electrical switch means actuated by the sensing of a significant

2

digit recorded in the card column appropriate thereto, electrical connections connecting one switch means with another, an electrical transfer line common to all said switch means, an input line connected to the switch means of lowest denomination, and an output line from each switch means representative of positive powers of ten, said electrical connections being such that an impulse along the input line is transferred to the transfer line by the first encountered actuated switch means representative of a negative power of ten and is directed thereby to the switch means representative of the highest positive power of ten to pass as a signal from the output line of the first encountered actuated switch means representative of a positive power of ten.

10 Apparatus according to the invention may also include a static network of coincidence gates to receive multiplicand digits sensed from a record card and to convert the sensed digits into a predetermined code, said decimal point selector being operative to control said network so that the sensed multiplicand issues therefrom in code and divided by a power of ten as determined by the decimal point selector, and pulse means operative in advance of the first of said addition periods to enter the multiplicand into the first counting register in two successive stages according to the values of divided sections of the multiplicand. Division of a digit may be effected by a diode pulse gate controlled by a diode coincidence gate, said coincidence gate being connected to the decimal point selector and the pulse gate to said pulse means. 15 The apparatus also includes a static network of coincidence gates to receive multiplier digits sensed from the card and to convert them according to a predetermined code, said network being controlled by said decimal point selector so that the sensed multiplier issues therefrom multiplied by a power of ten as determined by the decimal point selector.

20 To accommodate a multiplicand which is a sterling amount, the registers each comprise counters representative of tens-of-shillings, shillings, pence, and a plurality of counters selectively representative of digits to negative powers of ten or units of pounds and pounds to positive powers of ten.

25 In a preferred embodiment of apparatus according to the present invention a result obtained from a calculating operation is checked prior to a permanent record being made thereof and to this end the apparatus includes register reset means operative in succession to the readout means to reset the non-counting register and the first counting register prior to said pulse means being operative again to enter the multiplicand into the first counting register, complement pulse means operative in succession to the second entry of the multiplicand into the first counting register to apply a pulse to each counter of the first counting register thereby to set-up in the first counting register the complement of the multiplicand, means to enter a unit digit into the second counting register to accommodate the "fugitive" one, means to initiate a repetition of said groups of five addition periods each thereby setting up in the first counting register an amount representing the complement of the multiplicand multiplied by ten to a predetermined power thereof and under control of the transmit gate and multiplier digit selector successively reducing the amount set up in the second counting register until such amount is reduced to zero to check the accuracy of the multiplication of the multiplicand by the multiplier, and error trip means operable to effect cancellation of the set-up of the recording means in the event that a significant digit is registered in the second counting register on termination of the checking operation. The unit digit entering means may be operable during operation of the complement pulse means.

30 Apparatus according to the present invention may be

arranged to round-off a sterling product to the nearest penny or farthing and for this purpose the apparatus may include a manually selective device operative to effect entry into one or both of the counters representative of values 10^{-1} and 10^{-2} of a predetermined digit to effect rounding-off of the result in the second counting register to the nearest penny or to the nearest farthing.

It is a further object of the present invention to provide means whereby in the event of over-capacity being detected no permanent record is made of the result produced by the machine and accordingly apparatus according to the present invention also includes over-capacity detector means to effect operation of the error trip means on detection of a condition of over-capacity.

A still further object of the present invention is to incorporate in apparatus according thereto pulse generating means whereby pulses initiated by a multivibrator pass to a trigger circuit arranged to halve the frequency thereof and thence to a cycling unit comprising a four-stage divider of which each stage consists of a trigger circuit, said divider operating to generate a succession of pulses in groups of sixteen each and co-operating with gating means whereby the pulses of each group are entered to those parts of the apparatus to be operated thereby.

In order that the invention may be clearly understood one embodiment thereof will now be described, by way of example, with reference to the accompanying diagrammatic drawings in which:

In the ensuing description there will be described only the calculating apparatus according to the present invention, as the mechanism for feeding record cards into and through the machine, for sensing the cards, and for effecting the punching of a result therein may be of any suitable known form. The sensing mechanism employed is, however, such that when factors have been sensed from a record card, the sensing apparatus operates electrical contacts in a manner such that the contacts remain operated until the calculating apparatus has effected a calculation and also has effected checking thereof. Further, the punching mechanism for punching the result in a record card is of the kind which is conditioned electrically as the result of impulses read out from the result register of the apparatus according to the invention.

Fig. 1 illustrates a portion of a record card which can be employed in a machine embodying the apparatus according to the invention and from this figure it will be observed that the card includes a multiplicand field MCF, a multiplier field MF, and a product field PF. In Fig. 1 there are in the multiplicand field perforations representative of the sterling amount 13 shillings and 3.5 pence, in the multiplier field are perforations representative of the decimal number 24.05, and in the product field are perforations representative of the product £15, 19 shillings and 7.97 pence. The factors contained in the multiplicand and multiplier fields of the card shown in Fig. 1 will later be used in an example describing the operation of the apparatus according to the invention.

The apparatus according to the invention is arranged to operate in a manner such that when a multiplier contains a decimal fraction it is converted into a whole number and the multiplicand is divided by the power of ten by which the multiplier is converted to said whole number.

As will be described in detail below, multiplication is effected by repeated addition, the divided multiplicand being entered by two stages through a non-counting register R, Fig. 2A, into a first counting register CR1. The register R is reset to zero and the multiplicand set-up in the counting register CR1.

The multiplication operation can now be commenced and is effected in a predetermined number of groups of five addition periods each at the end of each, and groups of the amount standing in the first counting register CR1 is the multiplicand multiplied by a power of ten. During the first addition period of each group the amount then stored in register CR1, while being retained in CR1, is set up in register R, which is reset to receive it, and the amount so set up in register R is then, under control of cycling selector gates CSG cycled to the counting register CR1 and is added to the amount already registered therein, thereby doubling the amount registered in the counting register CR1. During the second addition period of the group the amount then stored in register CR1 is set up in the register R, the register R having been reset to receive it, and the amount so set up in register R is then cycled to register CR1 to be added to the amount already registered therein. The amount set up in the register R is also cycled to the register CR1 during each of the third, fourth, and fifth addition periods. A like sequence of operations is effected during each group of addition periods as will be more clearly illustrated below with reference to Fig. 11.

During each stage, under control of a multiplier coding network MPC, Fig. 2B, and the programme unit the partial products entered into register CR1 from register R are simultaneously entered into a second counting register CR2, Fig. 2B, so that, according to the digits contained in the multiplier, at the end of the last of the groups of addition periods the amount standing in register CR2 is the result of the multiplicand multiplied by the multiplier. The arrangement is such that should the multiplier digit be an odd number the first entry of register CR2 is during the entry into the register CR1 of the amount set up in register R during the first addition period of a group and, according to the value of the multiplier digit, the amount set up in register R during the second to fifth addition periods of a group will be entered selectively into the register CR2 as well as into register CR1.

Having given the foregoing brief description of the basis on which the apparatus according to the present invention operates, the apparatus and the mode of operation thereof will now be more particularly described, it being, for convenience, assumed that the necessary pulses for operating the apparatus are available as and when they are required. The manner in which the pulses are obtained and in which they are transmitted under control of the programme unit will be described at the end of the specification.

In Figs. 2A and 2B, for convenience of illustration, the sensing means for the multiplicand and for the multiplier has been indicated in two separate, spaced, positions.

It will, however, be understood that the sensing means employed for sensing a card and the electrical contacts operated thereby in practice comprise a single unit.

In Fig. 2A, the block MCSC represents the multiplicand sensing means and a coding and dividing apparatus, which latter is illustrated in Figs. 4 to 7, and the block MS represents the multiplier sensing. Adjacent to MS is a block MPC, Fig. 2B, representative of a multiplier

coding and converting network. The outputs from the apparatus MCSC and MPC are controlled by a decimal point selector DPS, Fig. 2A, which in the event that the multiplier sensed from the card field MF, Fig. 1, contains a decimal fraction and significant digits to the right of the decimal point determines the number of such significant digits and controls the division of the multiplicand and the conversion of the multiplier for transmission from MPC as a whole number.

10 The decimal point selector as illustrated in Figs. 3A and 3B comprises a plurality of electrical relays ER1, ER2 . . . ER8, one such relay being provided for each card column in the multiplier field MF. From Fig. 3B it will be observed that the relays ER1 . . . ER4 are representative of denominations for negative powers of ten and that relays ER5 . . . ER8 are representative of denominations for positive powers of ten. Each of the relays is connected to a positive line HT and, through a resistance ERS, to a line SDL connected to electrical 15 contacts MPS, Fig. 3A, which are closed by the sensing elements of the card sensing device. The sensing of a card is effected in any suitable known manner as for example by sensing pins, and as a result of the operation of the sensing means those sensing elements 20 which sense perforations in the record card effect the closing of electrical contacts MPS of which there are nine for each vertical column of the card field to be sensed. The nine contacts MPS, are, as indicated in Fig. 3A, representative of the digits 1 to 9 inclusive, no contact being 25 provided for a zero as it is customary, as shown in Fig. 1, not to punch zeros in the record card. Accordingly on sensing of a digit from the card field MF and closing of any contact MPS, the circuit of the appropriate relay ER is closed and two changeover contacts ERC1, ERC2 30 operated thereby, and hereinafter referred to as switches, are simultaneously changed-over from the normal positions thereof as shown in full lines in Fig. 3B. The switch ERC1 for relay ER1 which is the relay representative of the lowest denomination, that is 10^{-4} , is connected with an earth line ERE which constitutes an input line to the apparatus for controlling the division of the multiplicand sensed from the card and to the apparatus for controlling the conversion into a whole number of the multiplier sensed from the card should the multiplier include a decimal fraction. This connection 35 from the earth line ERE is made to one of five output lines DPS1, DPS2, DPS3, DPS4, DPS5 as determined by the positions of switches ERC1.

On closing of any of the contacts MPS, thus indicating 40 the sensing of a significant digit in the card column, connection is made to line SDL through a diode rectifier DR, Fig. 3A. The rectifiers DR are employed as buffering devices, as will be well understood, and from the succeeding figures of the drawings it will be observed 45 that, where necessary, similar diode rectifiers are also employed for this purpose.

The switches ERC1 are connected one with another as shown in Fig. 3B and, as shown in full lines in Fig. 3B, when inactive engage fixed contacts ERC11 but, as 50 indicated in dotted lines, when rendered active by the sensing of any digit in the card column appropriate thereto are changed over to engage fixed contacts ERC12. Each of the contacts ERC12 for relays ER1, ER2, ER3 and ER4 is connected to a transfer line TL, the arrangement being such that whenever a connection is made 55 along line ERE through a switch ERC1 which is changed over to its active position, the impulse is transferred to line TL and to the switch ERC1 of the relay ER8 which is the relay representative of the highest denomination 60 for a positive power of ten.

The switches ERC1 are set into the actuated or non-actuated positions thereof according to the digits sensed from the card field MF and one of the output lines DPS1 to DPS5 is connected to earth. These output lines are 65 at a positive potential to earth, unless this connection 70

is made. It will be seen from Fig. 3B, that if all the switches corresponding to digits of negative powers of ten are in the non-actuated condition, then line DPS5 is connected to earth irrespective of the digits of positive powers of ten. That is, all whole numbers result in line DPS5 being connected to earth. If any of the switches corresponding to negative powers of ten is in the actuated condition, the appropriate output line is determined by the significant digits of positive powers of ten. Thus if there is a digit in the 10^3 column, line DPS5 is connected to earth; if the highest digit is in the 10^2 column, line DPS4 is connected to earth; if the highest digit is in the 10^1 column, line DPS3 is connected to earth; if the highest digit is in the 10^0 column, line DPS2 is connected to earth; and if there are no digits in columns 10^3 , 10^2 , 10^1 , 10^0 corresponding to positive powers of ten, DPS1 is connected to earth.

In the machine described herein, the multiplier is always to be a four consecutive-digit number located anywhere on the eight digit field MF, that is, it is to be a four digit whole number with an associated power of ten, and the switches determine the appropriate power. Should more than four digits be sensed from a card, the four most significant are chosen by the switch. For example, should the multiplier sensed from the card be 124.05, the selector will choose the digits 1240 and will ignore the 5, which, consequently, will not be employed in the subsequent multiplication operation.

As an example of the mode of operation of the decimal point selector the operation thereof resulting from the sensing of card field MF, Fig. 1, will now be described. On sensing of the multiplier 24.05 as shown in the field MF, Fig. 1, relay ER3 is operated because of the 5 sensed in the column representative of denomination 10^{-2} . As there is a zero in the column representative of denomination 10^{-1} , this being denoted by the card column containing no perforation, relay ER4 is not actuated. In the column representative of denomination 10^0 relay ER5 is actuated as the result of sensing of the digit 4, and in column 10^1 relay ER6 is actuated to indicate the sensing of the digit 2. The impulse along line ERE passes through switch ERC1 for relay ER1, inactive, through switch ERC1 for relay ER2, inactive, to switch ERC1 for relay ER3, active, along line TL to switch ERC1 for relay ER8, inactive, switch ERC1 for relay ER7, inactive, to switch ERC1 of relay ER6, active, and thus along output line DPS3, indicative of two significant digits to the left of the decimal point in the sensed multiplier 24.05, to control the division of the multiplicand and the conversion of the multiplier to a whole number.

When, as the result of no perforation being sensed in a card column, a zero is to be transmitted to the apparatus for coding the multiplier and for converting it to a whole number, a signal indicative thereof is passed along line Z, Fig. 3B. This occurs when switches ERC1, ERC2 for a relay ER1 . . . ER8 have not changed-over as the result of the card sensing operation.

The multiplicand sensed from the card field MCF is coded and divided under control of the decimal point selector DPS in a static wiring network indicated generally in Fig. 2A by the block MCSC. The network is illustrated in detail in Figs. 4 to 7, of which Figs. 4 and 4A represent the network for one card column representative of decimal fractions of pence or of pounds. Figs. 6 and 6A represent the network for the card column representative of pence, and Figs. 7 and 7A represent the coding network for the column representative of shillings and tens-of-shillings.

As digits are sensed from the card field MCF, the sensing elements of the sensing device close contacts MCS completing circuits to output lines DCC1 which, through suitable resistances, are connected to a common input line IP to which a constant potential is applied. The lines DCC1 are arranged in groups, A, B, C, D, E,

5 F, G, H, J, K, a group consisting of one or more output lines described below. Each of the groups is, as can be seen from the drawings, arranged to convert a sensed digit into a coded form. From the drawings, it will be observed that the code for groups A, C, E, and J is the 1-2-4-2* code, coding for groups B and H is according to the 1-2-4-4* code, while groups D, F and K consist of a single line only representative of the Figure 1. Group G is also a single line and is representative of Figure 2.

10 In addition to the above the static wiring network includes five further networks all as shown in Figs. 4 and 4A and having groups of output lines DCC1 to be referred to hereinafter as L, M, P, Q, N, Fig. 4, each said group consisting of four lines to code digits according to the 1-2-4-2* code. The net work for groups L, M, N, P, Q is conditioned by the columns of the multiplicand field MCF representative of 10^{-1} pence, 10^{-2} , £1, £10, £100.

15 From the foregoing it will be understood that division of the multiplicand is effected by powers of ten and for apparatus to accommodate a sterling multiplicand and which, as in apparatus as herein described, ignores pounds except when DPS5, referred to above, is operative, there is obtained a table as follows:

	10^{-1}	10^{-2}	10^{-3}	10^{-4}
10/-	1/- 1.2d.	.12d. .12d.	.12d. .012d.	.012d. .0012d.
1/-	.1d.	.01d.	.001d.	.0001d.
1d.				

20 By reference to the table it will be understood that there will be occasions when in entering the divided multiplicand into the non-counting register R there are entries to be made in denominations 10^{-1} and 10^{-2} thereof of decimals of pence resulting from the division of both pence and shillings. These entries cannot be made simultaneously, and as the register R, Fig. 2A, is a non-counting register two amounts cannot be entered in succession without resetting the register between the entries. This contingency is accommodated by the apparatus according to the present invention by, in all instances, entering the divided multiplicand into the register CR1, which is a counting register, through register R in two stages 25 during the first of which the divided values of pence and decimal fractions of pence are entered and during the second the divided value of the units of shillings is entered.

25 From the above table it will be noted that whenever a divided value of tens-of-shillings, except when such value includes an additional sum of tenpence or elevenpence, is to be entered into register R there is no entry to be made in the corresponding pence denomination of register R. For example, 10 shillings and 3.5 pence divided by ten equal 1 shilling 0.35 pence. Thus the whole of these divided amounts can be entered at once into register R as each entry is into a different denomination of the register. Having regard to the exceptions just mentioned, when ten shillings and ten pence is divided by 10^2 the ten shillings equals 1.2 pence and the ten pence equals 0.1 pence, and the .2 pence and the .1 pence are entered into different trigger stages of register R. Accordingly, in the apparatus according to the invention, as will be illustrated below, the divided values of ten-of-shillings and of pence, including decimal pence, are entered into register R and the amount registered in R is cycled to register CR1 through cycling selector gates CSG, Fig. 2A, referred to below, and the divided values of units of shillings are entered separately into register R and into register CR1, the two divided values being added together in register CR1 to register the divided value of the multiplicand.

30 As has been mentioned above and as illustrated in Figs. 4, 4A, 6A, 7 and 7A a digit sensed from card field MCF is converted into coded form by the static network and for the decimal fractions of pence, Fig. 4, the lines from

the sensing contacts MCS are connected with a single group of four lines DCC1 so that the sensed digits are coded as follows:

Digit	Coded as
1	1
2	2
3	1,2
4	4
5	1,4
6	10
7	4,2*
8	1,2,4
9	2,4,2*

The non-counting register R, as illustrated in Fig. 5, consists of a single Eccles-Jordan trigger circuit representative of tens-of-shillings and each of the other denominations of the register consists of four such trigger circuits arranged according to the 1-2-4-2* or 1-2-4-4* code as shown in Fig. 5. Impulses along lines DCC1 are, subject to the control described below, entered into the trigger circuits corresponding to the digit values represented by the lines DCC1 in the register denominations appropriate thereto and impulses to the various register denominations are entered in parallel.

It will be understood that the division of decimal fractions of pence by powers of ten necessitates only the switching of the impulses on lines DCC1 to the appropriate register denomination. In the case of pence, shillings, and tens-of-shillings, however, division thereof will, in some instances, result in impulses having to be transmitted to two denominations of the register R and the manner in which this is effected is illustrated in Figs. 6, 6A and 7, 7A. From Figs. 6 and 6A it will be seen that on sensing of a digit a circuit is closed to lines of each of groups H and J or K of lines DCC1 and that groups J and K together consist of five lines two of which are representative of code figure 1. These two lines transmit impulses to trigger circuits representative of Figure 1 in different denominations of register R. Although on closing of sensing contacts MCS circuits are closed to both group H and group J or K effective impulses will pass along the lines of only one of the groups under control of the decimal point selector as described below.

From Figs. 7 and 7A it will be seen that the sensing contacts for the card column in which shillings and tens-of-shillings are recorded are connected with seven groups A, B, C, D, E, F and G of lines DCC1 and that in groups B and C a single sensed digit completes circuits representative of the value of sensed shillings in terms of pence. Thus, referring to Figs. 7 and 7A, it will be seen that a sensed 1 in the shillings column of card field MCF will close code circuit 1 in group B and 2 in group C, a 3 sensed from the card will close code circuit 1, 2 in group B representative of 3, and circuits 2, 4 in group C, representative of 6. Accordingly, by the network shown in Figs. 7 and 7A a shillings digit is in groups B and C expressed, in coded form, in terms of the number of pence the equivalent of the sensed shillings digit and division thereof by powers of ten can therefore be effected.

Each of the lines DCC1 of each group is, as illustrated in Figs. 4 and 4A, connected to one side of at least one diode coincidence gate DCG, Figs. 2A, 4, 4A and 5, the other side of the gate being connected, through a suitable resistance, to the decimal point selector DPS. The output line from the diode coincidence gate DCG is connected to a diode pulse gate DPG from which pulses from line DCC1 can pass to operate the appropriate trigger circuit of the register R. Thus, on closing of contacts MCS, resultant upon the sensing of a digit from card field MCF, the appropriate lines DCC1 condition one side of the diode coincidence gates DCG co-operating therewith and if simultaneously the gates DCG are conditioned by the decimal point selector DPS an output from a gate DCG conditions the gate DPG co-operating

therewith. The diode pulse gates DPG are only conditioned by the passage thereto of an impulse from the diode coincidence gates DCG and no pulse passes to the register R until to the diode pulse gates there is applied either a pence set pulse PSP transmitted thereto under control of the programme unit.

As stated above, Fig. 5 illustrates the non-counting register R and it will be observed that the register consists of nine denominational registering units representative respectively of coded figure values as illustrated in Fig. 5, in which figure the register units for denominations 10^{-3} , 10^{-4} , 10^{-5} , 10^{-6} , have been indicated as alternatives to decimal fractions of pence to register respectively thousands of pounds, hundreds of pounds, tens of pounds, and units of pounds when, under control of the decimal point selector, it is determined that no entries representative of decimal fractions of pence are to be made in register units 10^{-3} , 10^{-4} , 10^{-5} , 10^{-6} . If desired, the registering units 10^{-2} , 10^{-1} and pence may be similarly alternatively employed respectively to register, tens-of-thousands of pounds, hundreds-of-thousands of pounds, and units of millions of pounds.

Figs. 8A, 8B, 8C, 8D, 8E, 8F, 8G, 8H, and 8I together illustrate the register R and also indicate the manner in which impulses are received by each of the register units under control of the diode coincidence gates and the diode pulse gates. In the circles of the upper rows the letters indicate the group from which a pulse is received by the unit and the figure suffixed to the letter indicates the particular line DCC1 of the group along which the impulse passes. The circles of the lower rows represent the power of ten by which the multiplicand is divided, the controlling output from the decimal point selector DPS being indicated beneath the circles of the lower rows.

To further the understanding of the mode of operation of the static coding and dividing network and the manner of entry of a coded and divided amount into the register R, the entry of the amount 13 shillings 3.5 pence recorded in card field MCF, Fig. 1, will now be considered.

It has already been established above that for the problem represented by the card illustrated in Fig. 1 there will be an operative output from decimal point selector DPS along the output line DPS3 therefrom, thus it will be this decimal point selector output which is controlling the appropriate diode coincidence gates DGG. The decimal fraction of pence .5 pence sensed from the card enters the network appropriate thereto as illustrated in Figs. 4 and 4A so that on closing of sensing contact MCS the appropriate outputs from the gates DGG to which lines 1 and 4 of group L are connected are selected to pass through the gates DPG to the register R. Thus, as can be seen from Fig. 8F, on the application of pulse PSP to the gates DPG the trigger circuits 1 and 4 for unit 10^{-3} of register R are rendered active, thus registering .005 pence which is .5 pence to the power of 10^{-2} .

The digit 3 sensed from the pence column of card field MCF closes sensing contact MCS appropriate thereto, thus conditioning lines 1 and 2 in groups H and J. As therefore DPS3 is operative the gates DPG controlled thereby will permit the entry of pulses in the register in the unit 10^{-2} thereof, along lines DCC1 representative of figures 1 and 2 in group J, the amount thus registered being .03 pence which is 3 pence to the power 10^{-2} .

Also during the application of the pence set pulse PSP the amount of ten shillings sensed from the card is divided and transmitted to the register R, this being effected by the network shown in Figs. 7 and 7A along the single lines composing groups F and G which, under control of the decimal point selector output DPS3, causes an entry to be made in the register R in unit 10^0 , along line F1, and in unit 10^{-1} , along line G2, thus setting up in these units of the register the amount 1.2 pence which is 10 shillings (120 pence) to the power 10^{-2} .

At this time the register R registers the amount 1.235 pence which is 10 shillings 3.5 pence (123.5 pence) to

the power of 10^{-2} . This amount is transferred to the register CR1 and the register R is reset to receive the amount 3 shillings (36 pence) to the power of 10^{-2} , that is .36 pence.

The sensed digit 3 representative of 3 shillings closes the appropriate contact MCS in Fig. 7 thus conditioning lines DCC1 representative of figures 1 and 2 in groups A, B, and E. It also conditions lines representative of figures 2 and 4 in group C. As the pulse DPS3 from the decimal point selector is operative, on the application to diode pulse gates of the shilling set pulse SSP, a 3 (trigger circuits 1 and 2) will be registered in the register R in unit 10^{-1} along the DCC1 lines for 1 and 2 of group E, and a 6 will be registered in unit 10^{-2} along the DCC1 lines for 2 and 4 in group C. Thus, in register R there will be set up .36 pence which is 3 shillings (36 pence) to the power 10^{-2} . This amount is, in turn, transferred to the counting register CR1 to be added to the amount 1.235 already entered therein so that the register CR1 now registers 1.595 which is the multiplicand for the calculation to be effected and represents the sensed multiplicand 13 shillings 3.5 pence to the power of 10^{-2} .

Transfer of an amount registered in register R to register CR1 is effected through the cycling selector gates CSG which consist of diode coincidence gates, Fig. 10, connected with the register R through cathode followers CF4. Accordingly register R conditions gates CSG so that during the application of digit pulses DP1, DP2, DP4, DP2* or DP4* to the trigger stages of register R appropriate thereto, the number of pulses so applied being indicated by the figure which follows the suffix letters DP and which pulses are timed to occur in succession, as number of pulses corresponding to the value stored in register R pass from the output points of gates CSG to register CR1 through further cathode followers CF5, Figs. 2A and 10.

Except that the coded values ascribed to the counters of register CR1 are according to the 1-2-4-2* or 1-2-4-4* code the register is similar to register CR2 diagrammatically illustrated in Fig. 12, both registers CR1 and CR2 being, of course, provided with provision for effecting a carry from a counter of one denomination to the counter of next higher denomination.

From Fig. 10 it will be seen that the transfer of an amount from register R to register CR2 is also through the cycling selector gates CSG but entries to CR2 are controlled by transmit gates TG as will be described below.

Following the entry therein of the multiplicand as just described, the first counting register CR1 is now conditioned for the execution of the multiplication operation and the multiplicand is set up columnwise in the register CR1 as follows:

Counter	10^0	10^{-1}	10^{-2}	10^{-3}
Trigger Circuits	1	1 4	1 2	1 4

Figs. 9 and 9A illustrate the static network of coincidence gates by which the multiplier sensed from a card field MF is coded and converted into a whole number under the control of the decimal point selector DPS. Referring to Fig. 9 the coding is effected by a network of diode coincidence gates CDCG of which there are four for each denominational column in the card field MF. In the example illustrated in Fig. 1, the multiplier field of the card comprises eight columns of which four are for positive powers of ten and four are for negative powers of ten. The four diode coincidence gates CDCG are representative of figures according to the code 1-2-4-2*, as indicated in Fig. 9, the arrangement being

that the gates are all normally active and sensing of a digit in a card column renders inactive those gates other than those which are representative of the code representation of the sensed digit.

- 5 On sensing of the card, the sensing contacts MPS relative to the sensing elements of the sensing device which sense a perforation in a card column are closed thus transmitting to the gates CDCG, along lines SIL, impulses which reduce the potential at one side thereof.
10 The other sides of the gates CDCG are connected to input lines IMPG along which impulses MC1, MC2, MC4 and MC2* are received from programme unit gates PUG, Figs. 2B, 28B.

- 15 The impulses MC1, MC2, MC4 and MC2* are applied to lines IMPG during addition periods Nos. 3 to 22 during which, as described below with reference to Fig. 11, the divided multiplicand is, in register CR1 by successive addition, multiplied by ten thousand, and in register CR2 is in effect multiplied by the amount of the 20 whole number multiplier. The periods during which the impulses are effective is shown in the following table:

Impulse	CDCG gates conditioned during addition period			
	3	8	13	18
MC1-----	3	8	13	18
MC2-----	4	9	14	19
MC4-----	5 and 6	10 and 11	15 and 16	20 and 21
MC2*-----	7	12	17	22

- 30 On application to the gates CDCG of impulses along lines IMPG those gates to which impulses have been also imparted along lines SIL, Figs. 2B and 9, will be rendered inactive, whereas those gates which remain active will permit impulses to pass along lines OMPG connected thereto to a cathode follower CF1 which is connected to one side of a further diode coincidence gate DDCG. Thus on sensing a digit in the card field MF there is transmitted to the appropriate column of coincidence gates CDCG impulses representative of the complement of the sensed digit. For example, if the digit 1 is sensed in a card column it will be observed from Fig. 9 that impulses are imparted along lines SIL to the gates CDCG representative of code figures 2-4-2* which gates, on the application thereto of impulses along the lines IMPG, are rendered inactive so that only the gate representative of code figure 1 remains active and along the line OMPG from this gate passes an impulse sufficient to operate the appropriate cathode follower, CF1.

- 35 The opposite sides of the coincidence gates DDCG are connected with cathode followers CF2 which, in turn, are connected with the output points of further coincidence gates EDCG. One side of each of the gates EDCG is connected to a line SAL to receive pulses from programme unit gates PUG, Figs. 2B, 28A, 28B and 28C from which last mentioned gates are emitted pulses denoted as MP1, MP2, MP3, and MP4, Fig. 28C, and representative of the units, tens, hundreds, and thousands denominations of the converted multiplier.

- 40 The gates EDCG, Fig. 9A, are also connected with the decimal point selector DPS which is to control the conversion of the sensed multiplier to a whole number. This, as can be seen from Fig. 9A, is effected by the conditioning of gates EDCG by pulses along the appropriate lines SB1, SB2, SB3, SB4, SB5, which receive the DPS outputs. Since at any given time only one of the DPS outputs will be operative only one gate EDCG in each vertical column thereof will be conditioned thereby, thus only such one gate can be rendered active by pulses along the line SAL connected thereto. If, therefore, the uppermost gate of the leftmost column, as viewed in Fig. 9A, is conditioned by the DPS output, although the sensed significance of gates CDCG co-operating therewith is 10^{-4} on the application of a pulse along line SAL the significance of the sensed digit is changed to 10^0 .

- 45 The arrangement is such that the decimal point selector

conditions one side of each of the gates EDCG in each vertical column thereof, as viewed in Fig. 9A, thus on the application of a pulse to line SAL for any column, from that gate EDCG of the column which is conditioned by the decimal point selector an impulse passes from the output point thereof sufficient to operate the cathode follower CF2 connected thereto which, in turn, conditions the gate DDCG to which it is connected. The gate DDCG, if also conditioned by a pulse from the cathode follower CF1 connected thereto, permits outputs to pass to a further cathode follower according to the number of input pulses applied along the active line IMPG thereby applying to the transmit gates TG a number of pulses according to the value of the sensed multiplier digit for the particular denominational column of the multiplier.

As an example of the mode of operation of the network according to Figs. 9 and 9A, the coding and conversion of the multiplier 24.05 sensed from the card field MF, Fig. 1, will now be traced through the network. The digit 5 of the multiplier on being sensed is transmitted to the gates CDCG connected to the cathode follower CF1 (10^{-2}) in which network the gates representative of code figures 1 and 4 remain active; the zero in the multiplier renders inactive all of the gates connected to the cathode follower CF1 (10^{-1}); the digit 4 is transmitted to the gates CDCG connected to the cathode follower CF1 (10^0), only the gate representative of code figure 4 in this column remaining active; and the digit 2 sensed from the card is transmitted to the gate CDCG connected to the cathode follower CF1 (10^{-1}), only the gate representative of the code figure 2 connected to this cathode remaining active. It will be observed therefore that as a result of the sensing of the multiplier from the card field MF, conditioning pulses are applied to gates DDCG, through cathode followers CF1, for powers of 10^{-2} , 10^0 , and 10^1 . At this time, however, the decimal point selector DPS has determined that the multiplier has two significant figures to the left of the decimal and an output from DPS3 is operative. Accordingly, the output from line DPS3, Fig. 9A, is transmitted to each of lines SB1, SB2, SB4, and SB5, but not to line SB3. The reason for this is that the gates EDCG are normally active and are positive gates whereas the impulses from the decimal point selector are negative impulses. It is therefore necessary to invert the pulses from the decimal point selector and, accordingly, the pulses from the decimal point selector pull down each of the gates EDCG except those which are to remain operative. In the present instance as the result of the output DPS3 only those gates EDCG which are connected to line SB3 remain active. Accordingly when the units pulse is received along line SAL the gate DDCG (10^{-2}) is rendered active so that pulses pass therefrom representative of the units (MP1) denomination of the multiplier. Thus the digit 5 which was sensed as of the order 10^{-2} is now of the order 10^0 and impulses MC1 and MC4 pass from gate DDCG (10^{-2}) to the transmit gate TG, Figs. 2A and 10, to control the entry of partial products into register CR2.

During the application of pulses MP2, MP3, and MP4 to lines SAL there pass respectively from gates DDCG for powers 10^{-1} , 10^0 and 10^1 no impulses, impulses MC4 and impulses MC2 to the transmit gates TG to control the entry of partial products into register CR2.

Thus in the example given below, with reference to Fig. 11, the transmit gates TG will be open during addition periods 3, 4, 7, 15, 16, and 19.

In the foregoing description there has been described the manner in which the coded and divided multiplicand is, in two stages, entered into the first counting register CR1 on the application of pulses PSP and SSP to gates DPG. The two pulses PSP and SSP occur during the first two of twenty-two addition periods during the last twenty of which the multiplication operation is performed. The said last twenty addition periods, Fig. 11, are divided into four groups of five each as illustrated in

Fig. 11, and to which further reference will be made below.

The transfer of an amount from register CR1 to register R is controlled by pulses MCSP emitted from the programme unit gates PUG, Figs. 2B, 10 and 28B. Each stage of a counter of register CR1 controls a diode pulse gate forming a transfer gate CR1TG, Fig. 10, through which a negative pulse appropriate to each stage of the register CR1 can be transferred to register R upon the application of multiplicand set pulse MCSP. Thus the amount stored in register CR1 is transferred to register R by the pulses MCSP while remaining stored in register CR1.

During each group of five addition periods, Fig. 11, 15 digit pulses are applied to the gate CSG, as indicated in Fig. 10, the gates having been conditioned by the setting up of register R, operative pulses pass from the output points of gates CSG and so the amount stored in the register R is transferred to register CR1. If during any 20 addition period there should be applied to the transmit gate TG a pulse from the cathode follower CF3, then the amount being transferred by digit pulses DP1, DP2, DP4, DP2* or DP4* will also be entered into register CR2.

In order to further the understanding of the mode of 25 effecting a multiplication operation, it will be convenient now to describe the manner in which is effected a calculation using the factors sensed from card fields MCF and MF, Fig. 1.

Referring to Fig. 11, a register reset pulse RRR, Fig. 30 2B, is applied to registers R, CR1, and CR2, and then during the application of a set pulse PSP, the amount 1.235 is set up in register R and this amount, under control of the cycling selector gates CSG, is cycled to register CR1 so that the content of register CR1 is 1.235. The register 35 R is then reset by a reset pulse RR, Fig. 10, being transmitted to register R from the programme unit, Fig. 28A. Set pulse SSP then becomes operative and enters the amount .36 into register R, this amount, in turn, being cycled by the cycling selector gates CSG to register CR1 40 so that the content of this register is then 1.595 which is the sensed multiplicand divided by one hundred.

A further reset pulse RR, Fig. 2A, is applied to register R and then, on application of a pulse MCSP to gates CR1TG, the amount 1.595 stored in register CR1, while being retained in register CR1, is transferred to register 45 R.

On application of digit pulses during addition period 3, group 1, the amount 1.595 standing in register R is, under control of gates CSG, cycled to register CR1, the content of which then reads 3.19. During addition period 50 3 there is also applied to the transmit gate TG a pulse from cathode follower CF3 so that the amount 1.595 standing in register R is also transmitted to register CR2.

A reset pulse RR is again applied to register R and a 55 further pulse MCSP, addition period 4, causes the amount 3.19 to be transferred to register R. Thus during addition period 4 the amount 3.19 stored in register R is cycled to register CR1 so that the content thereof reads 6.38. During addition period 4 no pulse passes from cathode follower CF3 to gates TG and the amount so that the amount registered in CR2 remain 1.595.

During addition period 5 the amount 3.19 stored in register R is again cycled to register CR1 so that the amount registered therein is 9.57, but during this period 65 a pulse is applied to gates TG and the amount 3.19 is also transmitted to register CR2 so that the amount 4.785 is registered therein.

During addition period 6 the amount 3.19 stored in register R is cycled from register R to register CR1 so 70 that the content of register CR1 then reads 1/.076. During this period a pulse is applied to gates TG so that 3.19 is also entered into register CR2 so that this register now registers 7.975.

During addition period 7 the amount 3.19 stored in 75 register R is cycled to register CR1 so that the amount

registered therein is 1/-3.95, but during this period no pulse is applied to gates TG and the amount registered in CR2 remains 7.975.

It will be observed that during the addition periods 3, 5 and 6 there has been transmitted to register CR2 the amount stored in register R during these periods and it will also be noted that during addition period 3 there was transmitted to register CR2 the amount stored in register R which was the amount of the multiplicand divided by one hundred, whereas during the addition periods 5 and 6 the amount transmitted to register CR2 was, in each instance, twice the divided sensed multiplicand. Accordingly, the amount registered in register CR2 at the end of the units addition periods, that is the addition periods 3 to 7 comprising group 1, is five times the sensed and divided multiplicand and the divided multiplicand has accordingly been multiplied as required by the unit digit 5 of the converted multiplier 2405. It will also be seen that at the end of the units addition periods the amount registered in register CR1 is ten times the divided multiplicand.

Addition periods 8 to 12, group 2, are concerned with the tens digits of the multiplier, but as the multiplier 2405 has a zero in the tens denomination there will, as can be seen from Fig. 11, be no amount transmitted to the register CR2 during addition period 8 to 12.

At the start of addition period 8 the reset pulse RR is again applied to register R and a pulse MCSP controls the entry into register R of the amount 1/-3.95 now stored in register CR1. During the addition period the amount 1/-3.95 is cycled to register CR1 which, accordingly, then registers the amount 2/-7.90.

At the start of addition period 9 a further reset pulse RR is applied to register R and a pulse MCSP controls the entry into register R of the amount 2/-7.90 stored in register CR1. During this addition period the amount 2/-7.90 stored in register R is cycled to register CR1 which accordingly then registers 5/3.80.

During addition period 10 the amount 2/-7.90 is again cycled to register CR1 to register therein the amount 7/-11.70. During addition period 11 the amount 2/-7.90 is again cycled to register CR1 so that the amount registered therein is 10/-7.60, and during addition period 12 the amount 2/-7.90 is again cycled to register CR1 so that the content thereof is 13/-3.50.

Thus, at the end group 2 of addition periods the amount stored in register CR1 is equal to one hundred times the divided multiplicand 1.595 and, as mentioned above, the amount stored in register CR2 is still 7.975.

At the start of addition period 13, group 3, a further reset pulse RR is applied to register R and a further pulse MCSP then enters in register R the amount 13/-3.50 which at that time is stored in register CR1. During this addition period, which is the first of the periods for representative of hundreds in the multiplier, the amount 13/-3.5 is cycled from register R to register CR1 which then registers 6/-7.000001 (£1.6.7). During this period no pulse is applied to gates TG and, accordingly, the amount stored in register CR2 remains 7.975.

At the start of addition period 14 a further reset pulse RR is applied to register R and a pulse MCSP controls the entry of 6/-7.000001 into register R, this being the amount at that time stored in register CR1. During this addition period the amount 6/-7.000001 is cycled to register CR1 which, as a result, registers 13/-2.000002 (£2.13.2) but as no pulse is applied to gates TG the amount stored in register CR2 again remains 7.975.

During addition period 15 the amount 6/-7.000001 stored in register R is cycled to register CR1 so that the amount registered therein is increased to 19/-9.000003 (£3.19.9). Also during this addition period a pulse is applied to gates TG through cathode following CF3 so that the amount 6/-7.000001 is also transmitted to register CR2 to increase the amount stored therein to 7/-2.95001. (£1.7.2.975).

During addition period 16 the amount 6/-7.000001 is

again cycled to register CR1 so that the amount stored therein becomes 6/-4.000005 (£5.6.4). Also during this addition period there is applied to the gates TG a pulse from cathode follower CF3 so that there is transmitted to register CR2 the amount 6/-7.000001 and the amount stored in register CR2 is increased to 13/-9.975002 (£2.13.9.975).

During addition period 17 the amount 6/-7.000001 is again cycled to register CR1 to register therein 12/-11.000006 (£6.12.11) but as no pulse is applied to gates TG the amount stored in register CR2 remains unchanged.

From the description just given it will be seen that at the end of group 3 of addition periods the amount stored in register CR1 is one thousand times the divided multiplicand 1.595 and the amount stored in register CR2 is four hundred and five times the divided multiplicand 1.595.

At the start of addition period 18, group 4, a further reset pulse RR is applied to register R and is followed by a pulse MCSP which enters into the register the amount 12/-11.000006 then stored in register CR1.

Also during addition period 18, group 4, the amount 12/-11.000006 is cycled to register CR1 which then registers 5/-10.000013 (£13.5.10) but as no pulse is applied to the gates TG the amount stored in register CR2 remains unchanged.

At the start of addition period 19 a further reset pulse RR is applied to register R followed by a pulse MCSP which sets up in the register R the amount 5/-10.000013, the amount which is stored in register CR1, and the amount 5/-10.000013 is cycled to register CR1 which then registers 11/-8.000026 (£26.11.8). During this addition period, however, there is also a pulse applied to the gates TG and the amount 5/-10.000013 is also transmitted to register CR2 so that the amount registered therein is increased to 19/-7.975015 (£15.19.7.975).

During addition period 20 the amount 5/-10.000013 is again cycled to register CR1 which then registers 17/-6.000039 (£39.17.6) but as no pulse is applied to gates TG the amount stored in register CR2 remains unchanged.

During addition period 21 the amount 5/-10.000013 is again cycled to register CR1 to register therein 3/-4.000053 (£53.3.4) but as no pulse is applied to the gates TG the amount stored in register CR2 remains unchanged.

During addition period 22 the amount 5/-10.000013 is again cycled to register CR1 which then registers 9/-2.000066 (£66.9.2) but as no pulse is applied to gates TG the amount stored in register CR2 remains unchanged.

From the foregoing it will be seen that at the end of group 4 of addition periods register CR1 stores the amount £66.9.2 which is ten thousand times the divided multiplicand 1.595 pence and the register CR2 stores £15.19.7.975 pence which is two thousand four hundred and five times the divided multiplicand 1.595 pence and the multiplication operation has been completed.

From the foregoing description and from Fig. 11 it will be noted that during the calculation units of pounds were registered in the registers CR1 and CR2 in the counters 10^{-6} thereof and that tens of pounds were registered in the counter 10^{-5} thereof.

Fig. 12 illustrates diagrammatically the register CH2 and the four trigger circuits for the counters representative respectively of 1/-, 1 d., 10^{-1} , 10^{-3} , 10^{-4} , 10^{-5} , 10^{-6} , are to register according to the 1-2-4-8 code, and those for counter 10^{-2} are to register according to the 1-2-4-5 code. Each of the counters has connected to the last stage trigger circuit thereof a carry memory CM arranged, as described in the specification of co-pending application Serial No. 346,482, Eric John Guttridge et al., to store a carry until a carry pulse is applied to the register to effect carries in all counters of the register.

It will be noted that, in the construction as shown in Fig. 12, there is also a carry memory from the tens-of-shillings counter, which is the counter of highest denomination in the register, the carry pulse from the carry

memory CM for this counter being applied to the counter of lowest denomination, that is 10^{-6} . Thus whenever the product to be registered in register CR2 contains not more than two figures to the right of the decimal point, the four counters of lowest denomination can, as illustrated in Fig. 12, be employed to register pounds.

As stated above, the register CR1 is similar to CR2 and in the example described with reference to Fig. 11 it will be observed that in register CR1, during addition period 13, the amount cycled to register CR1 was such that the carry memory CM for the tens-of-shillings counter stored a carry which, on application of the carry pulse COP to the register, carried 1 to the 10^{-6} counter thereby registering therein £1. It will be noted that a similar action was effected for register CR2 during addition period 15.

It will also be noted from Fig. 12 that the register CR2 includes pairs of double triode valves PT1, PT2, the arrangement of each pair being such as to provide four valves one for each of the trigger circuits contained in the appropriate counter. The triodes PT1 and PT2 form part of the read-out mechanism whereby a result registered in CR2 can be transmitted to the decoding device for a punch unit not shown, but which may be of a character similar to that described in the specification of co-pending application Serial No. 200,749, John Perrin, filed December 14, 1950. It will be understood, however, that the result which is recorded in the product field PF of a card Fig. 1, is made by perforations representative of digits recording a sterling amount. Thus, as the amount registered in register CR2 is registered according to code, the product must be decoded prior to setting the punches to effect a punching operation on the card. Decoding apparatus operable as the result of a reading-out operation from a calculating machine and arranged to co-operate with a punch mechanism is known in the art and, when the machine is an electrical calculating machine, as is that described herein, the decoding mechanism is controlled by solenoids S, Fig. 13, one solenoid 3 being provided for each trigger circuit of each counter of the register CR2.

Referring to Figs. 13 and 14 a reading-out operation is initiated by normally closed cam operated switches RO1 and RO2, Fig. 15, the cams, not shown, being operated simultaneously in timed relationship with the operating mechanism for effecting operation of the punch mechanism.

In Fig. 13 are illustrated read-out lines CRO for the 10^{-3} counter of register CR2 each such line being connected to a triode PT3 which, in turn, is connected to the solenoid S for the particular counter circuit. It is assumed that TOP is the output from the trigger circuit representative of 4 in counter 10^{-3} and that the output point TOP of the trigger circuit in its non-registering condition is at a lower potential than it is when it is in its registering condition. Thus, if on opening of the cam operated read-out switch RO1 the potential at TOP is at its higher value to indicate that the trigger circuit is registering, the solenoid S co-operating therewith will be energised and will operate to control the de-coding device which co-operates with the punch mechanism. On the other hand, if when the read-out switch RO1 is opened the potential at TOP is at its lower value, indicating that the trigger circuit is not registering, then the solenoid S co-operating therewith will not be energised.

Fig. 14 illustrates a part of a read-out circuit similar to that of Fig. 13, but which is specific to the 10^{-1} and 10^{-2} counters of register CR2. It will be understood that for all counters of register CR2, other than the 10^{-1} and 10^{-2} counters, there is a read-out circuit as shown in Fig. 13.

The read-out circuit for the 10^{-1} and 10^{-2} counters differs from the others because, in the machine being described, the amount registered in these two counters may, as described below, be rounded off and converted into terms of farthings. To this end the read-out circuits for counters 10^{-1} and 10^{-2} are controlled by the read-out switch RO2 and also by a round-off switch ROS, Figs. 21

and 22, described below, and the amounts registered in these two counters are not subjected to a checking operation as are the other counters of the register, accordingly the outputs from the 10^{-1} and 10^{-2} counters are not connected to a cathode follower CF20 as shown in Fig. 13. From Fig. 22 it will be observed that switch RO2 is connected directly to earth but from Fig. 13 it will be seen that RO1 is connected to earth through a normally closed operated switch ETS, referred to below. Thus when, as seen from Fig. 18, the switches RO1 and RO2 open at 80° they permit reading out from all counters of the register CR2. When, however, reading out is effected after a checking operation, described below, switches RO1 and RO2 are both closed and the reading out is controlled by the switch ETS which, see Fig. 18 opens at 250° . Opening of switch ETS as can be seen from Fig. 13, is the equivalent of opening switch RO1 so the equivalent of a reading-out operation is effected for all counters of register CR2 except counters 10^{-1} and 10^{-2} .

As was mentioned above, and as illustrated in Fig. 11, certain of the counters of register CR2 are arranged to register either decimal fractions of a penny or denominational values of pounds. It will, however, be understood that, each counter, during a calculating operation, registers only one or other of such values. Determination as to whether or not values registered in the counters 10^{-3} , 10^{-4} , 10^{-5} , 10^{-6} represent pounds, in which event they are read-out, or decimal fractions of a penny, in which event they are not read-out, is by the decimal point selector DPS as shown in the following table, the decimal point selector being conditioned for a four figure multiplier.

Register CR2 Counter	Decimal point selector setting				
	DPS1	DPS2	DPS3	DPS4	DPS5
35					
10^{-3}	Not Read out 10^{-3} D	Not Read out 10^{-3}	Not Read out 10^{-3}	Not Read out 10^{-3}	Read Out $\text{£}10^1$
10^{-4}	Not Read out 10^{-4}	Not Read out 10^{-4}	Not Read out 10^{-4}	Read Out $\text{£}10^2$	Read Out $\text{£}10^2$
10^{-5}	Not Read out 10^{-5}	Not Read out 10^{-5}	Read Out $\text{£}10^1$	Read Out $\text{£}10^1$	Read Out $\text{£}10^1$
10^{-6}	Not Read out 10^{-6}	Read Out $\text{£}10^0$	Read Out $\text{£}10^0$	Read Out $\text{£}10^0$	Read Out $\text{£}10^0$

The method of determination is illustrated in Fig. 13 and is such that when lines CRO are at a low potential, either because the decimal point selector or the read-out switch RO1 is earthing thereon, opening of the switch RO1 will not cause energisation of solenoids S. If, however, lines CRO are at a low potential because the read-out switch RO1 is earthing them and the decimal point selector is not, then opening of switch RO1 will permit energisation of the appropriate solenoids S.

The mode of operation of the read-out circuit can be more clearly understood by referring again to the example given above with reference to the factors sensed from the card shown in Fig. 1. In the example the result or product registered in CR2 was £15.19.7.975 pence and this was registered in register CR2 as follows:

Counter	Trigger circuits Registering	Amount Registered
65		
10^{-1}	Registering 1 and 8 registering	$10/-$
10^{-1}	1, 2, 4, registering	$9/-$
1d	1, 2, 4, registering	7d.
10^{-1}	1 and 8 registering	.9d.
10^{-2}	1, 2, 4, registering	.07d.
10^{-3}	1 and 4 registering	.005d.
10^{-4}	None registering	0.000
10^{-3}	1 registering	£10
10^{-4}	1 and 4 registering	£ 5

On reading out this result, as DPS3 is connected to earth, the values in all register counters except the 10^{-3} and 10^{-4} counters will be read-out and transmitted to the

solenoids S appropriate thereto. The values registered in the counters 10^{-3} and 10^{-4} are ignored by the read-out mechanism and the values in the 10^{-5} and 10^{-6} counters will effect energisation of the solenoids S co-operating with the columns of the punch unit appropriate respectively to tens of pounds and units of pounds.

The result read out from register CR2 is in coded form and the solenoids S are part of a decoding device co-operating with the punch unit. To facilitate the operation of the mechanical elements of the decoding apparatus it is necessary to retain the energised solenoids S in their energized condition for an interval longer than that provided by the read-out impulses to the solenoids S. To this end there is provided a normally open cam operated switch HCS, Figs. 13 and 15, which controls a holding circuit HC, Fig. 13, for solenoid S.

If as the result of the checking operation an error is detected in the result set-up in register CR2, means described below is provided to cancel the setting of the punches, thereby preventing punching of the incorrect result in the card.

Checking is effected by setting up in register R the complement of the divided multiplicand and then multiplying the said complement by ten thousand as described above, making the appropriate deductions from the amount set up in register CR2. The checking operation will be described with reference to Figs. 16 and 17, which latter figure illustrates the checking of the result obtained in the example illustrated in Fig. 11.

At the start of the checking operation, a reset pulse MR, Fig. 2B, resets registers R and CR1 and then a pence set pulse PSP sets into register R the amount 1.235, register CR2 at this time registering 19/-7.975015 which is the result obtained from the calculation illustrated in Fig. 11. A complement pulse CP is then applied to each trigger circuit of register R as illustrated in Fig. 16, thus reversing the setting in register R which, accordingly, is then set at 19/-10.764999.

Fig. 16 illustrates one column of the register R and the four trigger circuits for registering digits according to the 1-2-4-2* code. Each of the trigger circuits has three input lines of which one, as shown in Fig. 16, receives the normal registering pulses PSP, SSP and MCSP, line RR1 receives the register reset pulse RR, and line RE is a reset line normally connected to earth. The complement pulse CP is applied to lines RR1 and RE. Thus when the complement pulse CP is applied to the circuit each of the trigger circuits is reversed so that the trigger circuits represent, according to code, the complement of the value set up therein before the application of the complement pulse. To facilitate the understanding of the operation of the complement pulse to register R, the effect of the complement pulse on the first entry into the register when the first part of the divided multiplicand is set up will be considered. The first entry into the register R, as shown in Fig. 17, is 1.235 and is set up columnwise in the register R as follows:

Register Column	Trigger Circuits Registering	Value registered
10/-	None	0
1/-	None	0
1d.	1	1d.
10 ⁻¹	2	.2
10 ⁻²	1 and 2	.03
10 ⁻³	1 and 4	.005
10 ⁻⁴	None	0
10 ⁻⁵	None	0
10 ⁻⁶	None	0

When the complement pulse CP has been transmitted the columnwise set-up in register R is as follows:

Register Column	Trigger Circuits Registering	Value Registered
10/-	Registering 1, 2, 4, and 2*	10/-9/-
1/-	2, 4, and 4*	1d.
1d.	1, 2*, and 4	.7
10 ⁻¹	2* and 4	.06
10 ⁻²	2 and 2*	.004
10 ⁻³	1, 2, 4, and 2*	.0009
10 ⁻⁴	1, 2, 4, and 2*	.00009
10 ⁻⁵	1, 2, 4, and 2*	.000009
10 ⁻⁶	1, 2, 4, and 2*	.000009

It will be noted that the coding employed for complements is different from that as set out above with reference to Fig. 4, but this is of no consequence.

Under control of the cycling selector gates CSG, the amount now set up in register R is cycled to register CR1 which accordingly registers 19/-10.764999. A reset pulse RR is then applied to register R after which a shillings set pulse SSP enters into register R the amount .36, this being followed by a further complement pulse CP whereby the trigger circuits of register R are reversed to register the complement of the amount .36 set up therein, this complement being 19/-11.639999. Under control of gates CSG this amount is cycled to register CR1 and is added to the amount already standing therein so that the amount now set up in the register is 19/-10.404999. It will be understood from the foregoing description that when adding the two amounts entered into register CR1 there is caused a carry from the tens-of-shillings trigger circuit which is carried over to the 10^{-6} or lowest trigger circuit. There is, of course, also a carry effected from the pence to the shillings trigger circuit.

It will be understood that, at some time during the 35 checking operation, provision must be made in register CR2 for the condition known in the art as the "fugitive one" and, although this could be accommodated at any suitable stage, it is convenient in the apparatus as described herein to insert the "fugitive one" into register CR2 at the same time as the complement pulse CP is applied to register R during addition period 2. For convenience, in the apparatus herein described, the counters 10^{-1} and 10^{-2} of register CR2 are not checked and the "fugitive one" is entered into the counter 10^{-2} . Accordingly, at the end of addition period 2, the "fugitive one" has been added to the amount set up in register CR2 and the amount registered therein is now 19/-7.985015.

At the conclusion of addition period 2, register R is 50 reset by a reset pulse RR and a pulse MCSP enters into register R the amount set up in register CR1 which at this time is 19/-10.404999. Under the control of gates CSG this amount, during addition period 3, group 1, is cycled to register CR1 which thereupon records 19/-8.809999. At this time, however, a pulse is also applied to transmit gates TG so that the amount set up in register R is also transmitted to register CR2 so that in this register there is now registered 19/-6.390015 (£15.19.6.39).

60 A further reset pulse RR is applied to register R and a pulse MCSP enters into register R the amount at this time set up in register CR1 which is 19/-8.809999. During addition period 4 this amount is cycled to register CR1 to register 19/-5.619999 therein. A pulse is not 65 applied to transmit gates TG so that the amount registered in CR2 remains 19/-6.390015 (£15.19.6.39).

During addition period 5 the amount set up in register R is again cycled to register CR1 to record 19/-2.429999 therein. During this period, however, a 70 pulse is applied to transmit gates TG so that the amount cycled to CR1 is also transmitted to CR2 which as a result registers 19/-3.200015 (£15.19.3.2).

During addition period 6 the amount stored in register R is again cycled to register CR1 to register 75 18/-11.239999 therein and a no pulse is applied to trans-

mit gates TG so that the amount cycled to CR1 is also transmitted to CR2 to register therein 19/-0.010015 (£15.19.0.01).

During addition period 7, the amount stored in register R is again cycled to register CR1 to register 18/-8.049999 therein but during this period no pulse is applied to transmit gate TG so that the amount in register CR2 remains 19/-0.010015 (£15.19.0.01.).

From the description just given of the mode of checking in so far as it relates to the units addition periods, group 1, of the multiplier, from Fig. 17 and from the earlier description of Fig. 11, the succeeding steps of the checking operation will be obvious without further description thereof. Each step of the checking operation is, however, fully illustrated in Fig. 17 and from this figure it will be observed that at the end of addition period 22, group 4, the register CR1 registers an amount which is equal to ten thousand times the complement of the divided multiplicand 1,595, and register CR2 registers zero in all columns except column 10⁻² which, as stated, is a column which it is desired not to check.

It will, however, be readily understood that, if desired, columns 10⁻¹, and 10⁻² can also be checked and, in such event, the fugitive one instead of being applied as just described will be applied at the end of the checking operation and just before its application to the 10⁻² counter the carry connection between the 10⁻³ counter and the 10⁻² counter will be broken so that the register CR2 is restored to zero.

The reason in the present apparatus for not effecting checking of columns 10⁻¹ and 10⁻² of register CR2 is that, as will be described below, it is often desired to round-off the amount registered in these two columns to the nearest farthing and when this is done, it is necessary to insert into one or both of these two columns a digit or digits to control the rounding off operation.

When the checking operation is completed a normally closed cam-operated switch ETS, Figs. 13 and 15, is opened so that reading out is effected from each of the counters of register CR2 except counters 10⁻¹ and 10⁻² as described above. Each of the read-out circuits controlled by switch ETS is connected through a triode CF20, Fig. 13, to one side of a diode coincidence gate GDCG. The other side of gate GDCG is normally connected to earth through a lead ETL and the switch ETS referred to below as an error trip switch. The output point from gate GDCG is connected with a triode PT5 which, in turn, is connected with an error trip relay ETR. The arrangement is such that, if on opening of switch ETS each of the counters from which reading out has been effected registers zero, as it should do in the event that the checking operation has determined that the previous calculation was correctly performed, then the output voltage from gates GDCG will be insufficient to energise relay ETR and consequently the punch setting which resulted from the reading-out operation on opening of switches RO1 and RO2 is permitted to stand and, at the proper time, the punches will punch the result in the card as has been indicated in Fig. 1 in field PF thereof.

If, however, as the result of a checking operation one or more of the trigger switches of those counters of register CR2 shown in Fig. 13 is not restored to its reset or zero condition when switch ETS opens the output voltage from gate GDCG will energize relay ETR. As can be seen from Fig. 19, a contact of relay ETR is in circuit with an A. C. reset solenoid RS. The solenoid RS is included in the punch setting mechanism for the purpose of resetting the set bars thereof, but under control of the relay ETR is rendered effective to reset the set bars prior to a punching operation being performed so that, in the event of an error being detected as the result of the checking operation, the punches are reset and the incorrect result is not punched in card field PF. The solenoid RS is also operated under control of a normally open cam-operated switch PRS, Fig. 15, which switch controls sole-

noid RS to effect resetting of the punch bars after a punching operation has been effected.

The solenoid RS, as can be seen from Fig. 19, is also controlled by a relay OCR to be referred to below.

Referring to Fig. 1, the result £15.19.7.97 of the calculation effected from the multiplicand and multiplier punched in the card is punched in card field PF with the decimal fraction of pence. If desired, however, the decimal fraction of the penny may be expressed and punched in card field PF in terms of farthings and to this end apparatus according to the present invention includes a farthings decoding unit, Figs. 20 and 20A, which co-operates with the 10⁻¹ and 10⁻² counters of register CR2. When determining the nearest farthing from counters 10⁻¹ and 10⁻² it will be understood that the digit registered in counter 10⁻¹ is the controlling digit and that that registered in counter 10⁻² is of interest only in so far as the digit is below 5, or is a 5, or is greater than 5. In decoding any amount less than .25 is ignored. An amount of from .25 to .49 is considered as 1/4d., from .5 to .74 is considered as 1/2d., and .75 to .99 is considered as 3/4d. From Fig. 12, it will be noted that the counter 10⁻² differs from the other counters of register CR2 in that the four trigger circuits thereof represent digits according to the 1-2-4-5 code. In Figs. 20 and 20A, the counters 10⁻¹ and 10⁻² are diagrammatically illustrated, the four trigger circuits for counter 10⁻¹ being enumerated respectively as S1, S2, S3, S4 and those for counter 10⁻² being enumerated S1, S2, S3, S5. It will be understood that the only reason for the last stage of counter 10⁻² being enumerated S5 is to distinguish it from the last stage trigger circuit S4 of counter 10⁻¹ since so far as counter 10⁻² is concerned, for the purpose of rounding-off, only the condition of the last stage S5 is relevant.

In each of the registers R, CR1, CR2 the trigger circuits by which digits are registered are arranged so that a digit is registered when the anode A0 of a trigger circuit is non-conducting. Thus in counter 10⁻¹ of register CR2 digits are registered as follows:

	Digits	Anode non-conducting
0	S1A1; S2A1; S3A1; S4A1.	
1	S1A0; S2A1; S3A1; S4A1.	
2	S1A1; S2A0; S3A1; S4A1.	
3	S1A0; S2A0; S3A1; S4A1.	
4	S1A1; S2A1; S3A0; S4A1.	
5	S1A0; S2A1; S3A0; S4A1.	
6	S1A1; S2A0; S3A0; S4A1.	
7	S1A0; S2A0; S3A0; S4A1.	
8	S1A1; S2A1; S3A1; S4A0.	
9	S1A0; S2A1; S3A1; S4A0.	

It will be understood that when this counter registers 0 or 1 it can be ignored for the purpose of decoding to farthings, but when it registers 3 or 4 it is a 1/4d.; when it registers 5 or 6 it is a 1/2d., and when it registers 2, the condition of stage S5 of counter 10⁻² is relevant as to whether the denomination is zero or a 1/4d.; when it registers 7 the condition of stage S5 of counter 10⁻² is relevant as to whether the denomination is a 1/2d. or 3/4d., and when it stands at 8 or 9, it will be decoded as 3/4d. Thus, for decoding it is not necessary to explore all stages of the counter 10⁻¹ to determine decoding and the following table shows the parts of the counter which are explored in this respect by the circuit arrangement illustrated in Figs. 20 and 20A.

Digit	Anodes non-conducting	Decoded
2	S1A1; S2A0; S3A1; S5A0	1/4d.
3	S1A0; S2A0; S3A1	1/4d.
4	S1A1; S2A1; S3A0	1/2d.
5	S1A0; S2A1; S3A0	1/2d.
6	S1A1; S2A0; S3A0	1/2d.
7	S1A0; S2A0; S3A0; S5A1	3/4d.
8 or 9	S1A0; S2A0; S3A0; S5A0	3/4d.

Figs. 20 and 20A illustrate the decoding as set out in the table above and from Figs. 20 and 20A it will be seen that whenever the decoding indicates that $\frac{1}{4}d$. is to be recorded an output along a line FL1 passes through a cathode follower CF6 to a solenoid FS1 to condition the appropriate set bar of the punch unit for punching a perforation indicative of $\frac{1}{4}d$. in card field PF. Similarly, when the decoding network indicates that $\frac{1}{2}d$. is to be recorded, an impulse passes along a line FL2 through a cathode follower CF7 to energize a solenoid FS2 to control punching of a perforation representative of $\frac{1}{2}d$., and an impulse along line FL3 passes through a cathode follower CF8 to energize a solenoid FS3 controlling the punching of a perforation representative of $\frac{3}{4}d$. The farthings outputs are subject, along lines FC, to the overriding control of the round-off switch ROS, Fig. 22, so that they are effective only when the switch ROS is set for this purpose.

In some instances, it may be desired to round-off results to the nearest penny or to the nearest farthing and apparatus according to the present invention includes means to facilitate this operation, such apparatus being illustrated in Fig. 21.

In the description given above of the mode of checking a calculation, reference was made to the insertion of a "fugitive one" into the counter 10^{-2} during the application of the second complement pulse CP to register R. If rounding-off is to be effected, a "fugitive one" is entered into register CR2 only when, during the application of the second complement pulse to register R, no predetermined amount, as described below, is entered into one or both of the counters 10^{-1} , 10^{-2} of register CR2. Entry of the predetermined amount into counters 10^{-1} , 10^{-2} of register CR2 is controlled by the manually operated switch ROS, Figs. 21 and 22, settable prior to the commencement of a calculating operation, and according to the setting of the switch, the amount entered into counters 10^{-1} , 10^{-2} during the application of the second complement pulse to register R is as follows:

Rounding-off switch position No.—	Result to be rounded off to—	Predetermined amount entered in CR2
1.....	nearest $\frac{1}{4}d$	.12
2.....	next higher $\frac{1}{4}d$	.24
3.....	next lower $\frac{1}{4}d$	.00
4.....	nearest 1d.....	.49
5.....	next higher 1d.....	.99
6.....	next lower 1d.....	.00

From the above table it will be observed that no additions are made in switch positions numbers 3 and 6 and from Fig. 21 it will be observed that there is also a switch position No. 7 in which position of the switch no addition is effected. The No. 7 position of the rounding-off switch ROS is the position of the switch when, instead of being rounded-off in accordance with the table, the result is to be punched in terms of decimal fractions of pence as is shown in card field PF, Fig. 1.

From Fig. 22, it will be observed that the rounding-off switch ROS consists of three banks each having seven contact positions of which bank 1, positions 1, 2, 4, 5, Fig. 21, controls the amount to be added into counters 10^{-1} , 10^{-2} of register CR2 during the second complement pulse as aforesaid, and on positions 3, 6 and 7 controls the fugitive one gate FOG, Fig. 28C, so that the "fugitive one" is entered into the register only when the switch is set at one of these positions.

Referring to Fig. 22, the reading out from counters 10^{-1} and 10^{-2} of register CR2 and from the farthings decoding apparatus is subject to the overriding control of banks 2 and 3 of switch ROS. The lines CRO, Fig. 14, are held at a low potential by bank 2, positions 1 to 6 inclusive, so that when the switch is set to any one of these positions solenoids S co-operating with counters

10^{-1} and 10^{-2} of register CR2 will not be energised. When, however, the switch is set at position 7 the solenoids can be energised when the read-out switch RO2 opens.

The lines FC, Figs. 20 and 20A, are held at a low potential by bank 3, positions 4 to 7 inclusive, so that when the switch is set to any one of these positions the solenoids FS1, FS2, and FS3 will not be energised. When however, the switch is set in any of positions 1, 2, or 3 thereof the solenoids can be energised when the read-out switch RO2 opens.

Fig. 21 illustrates the manner in which the rounding-off switch controls the entry of amounts into the 10^{-1} and 10^{-2} counters of register CR2 and from this figure it will be observed that contacts Nos. 1, 2, 4, and 5 of switch ROS are each connected to one side of a diode coincidence gate HDCG, the opposite sides of which are connected through cathode followers CF9 to the output points of further diode coincidence gates KDCG. One side of each of gates KDCG is connected through a cathode follower CF10 with a further diode coincidence gate LDCG and the other side of each gate KDCG is connected with a line to receive digit indicating pulses as indicated in Fig. 21. The gate LDCG is arranged to receive pulses MACS1A0, MACS2A1, and CCA1 from the A0, A1, and A1 anodes of stages S1 and S2 of the trigger circuits MAC, Fig. 26, and from the trigger circuit CC, Fig. 26.

As an example of the mode of operation of the rounding-off switch ROS, let it be assumed that, as illustrated in Fig. 21, the switch is set at position No. 1. There is an output from LDCG with input pulses MACS1A0, MACS2A1, and CCA1, Fig. 27A, only during the second addition period of the calculation operation, and therefore one group of digit pulses is gated through gates KDCG during this period. It will be noted that the outputs from gates KDCG are one pulse, two pulses, four pulses, and nine pulses as indicated in Fig. 21; the nine pulses being obtained by mixing DP1, DP2, DP4 and DP2* at the input point MI. Only those gates HDCG which are connected to contact 1 of switch ROS will permit the passage of an output to register CR2 on the application of input thereto of pulses 1, 2, 4 or 9. Thus, as can be seen from Fig. 21, a single digit representing pulse will pass to counter 10^{-1} of register CR2 and two digit representing pulses pass to counter 10^{-2} , thus adding into register CR2 the amount .12.

The apparatus herein described is designed to perform calculations in sterling either with a multiplicand containing only shillings and pence and decimal fractions of pence, and a multiplier which contains a decimal fraction or, if the multiplier is a whole number, then the multiplicand may include pounds. In each instance, however, the register CR2 has a maximum capacity which, if exceeded, will cause an incorrect result to be registered.

The following conditions are, in the machine herein described, considered as representing conditions of "over-capacity":

Over-capacity—condition 1

This condition can occur when the multiplicand includes no pounds, register CR2 stores an amount near to the maximum capacity thereof, the decimal point selector is giving an output DPS1 or DPS2, and the round off-switch ROS is set for rounding-off. In these circumstances the addition to counter 10^{-1} or 10^{-2} of register CR2 of the one of the predetermined amounts to effect rounding-off may cause the maximum capacity of the register to be exceeded.

Over-capacity—condition 2

The maximum capacity of the register CR2, as described herein, is £9999-19-11.99d. Should the multiplicand include pounds and the multiplier be a high whole number the product may exceed the maximum capacity of the register. Detection of this condition of over-capacity must be effected in a number of register CR2 inputs since the

result may go over-capacity in more than one way during the calculation. The result accumulator itself may go over capacity, which condition is indicated by a carry from the £10³ counter into the 10⁻² counter, or the entry to the result accumulator may be over-capacity in which case an entry representing £10⁴ is made into the 10⁻²d. counter through the transmit gate TG after the first group of addition periods, or an entry representing £10⁵ is made into the 10⁻¹d. counter through the transmit gates TG for the second group of addition periods. If the entry is not over-capacity there will be no entry via these routes

Over-capacity—condition 3

This condition can occur if the multiplicand includes pounds and the multiplier includes a decimal fraction. In such an event the pounds would be ignored by the static coding and dividing network of Figs. 4 to 7 as it contains no provision for the division of pounds. To avoid incorrect results being entered into register CR2 in such circumstances a test is applied during the input of the multiplicand and the multiplier.

Over-capacity—condition 4

The entry to register CR2 through the transmit gates TG of the result of a calculation using a multiplicand of £500 and a multiplier of 2,000, 4,000, 6,000 or 8,000 results in an over-capacity as in such instances an entry representing £10⁶ could be made to the pence counter. Such over-capacities are not easily detected as it is found that when they occur there may be other pulses simultaneous therewith which cause confusion. This kind of over-capacity is, therefore, detected by an input test resulting in rejection of a card containing a perforation in the multiplicand column £10² and also a perforation in the multiplier column 10³.

Fig. 23 is a diagram illustrating the means by which the over-capacity relay OCR is operated as a result of the detection of one of the conditions of over-capacity as above set forth. Conditions 3 and 4 are detected as the result of input tests and a signal is held throughout the calculation and check periods until opening of the error trip switch ETS, Fig. 13, when relay OCR is energized by the signal. Conditions 1 and 2, however, are transitory and occur during the calculation thus rendering it necessary to store or memorise the condition until opening of switch ETS.

Referring to Fig. 23 it will be seen that all tests for over-capacity are effected by coincidence gates MDCG, NDCG, ODCG, PDCG, QDCG, RDCG, or SDCG, those of a transitory character being stored in an Eccles-Jordan trigger circuit EC2 and mixed with input over-capacity signals at MIX. Gates MDCG and NDCG detect condition 1, gates ODCG, PDCG, and QDCG detect condition 2, gate RDCG detects condition 3, and gate SDCG detects condition 4.

From Fig. 23 it will be seen that one side of each gate MDCG, NDCG and ODCG, is connected to the carry memory CM for one of the counters of register CR2 and the other side of the gate is connected to the output of an Eccles-Jordan trigger circuit EC1 which is triggered by the round-off gating pulse ROGP, Fig. 21, and by the master reset MR, Fig. 2B. This arrangement is provided because the condition of over-capacity detected by these gates may occur after the calculation stop signal, provided by pulse CCA1, Fig. 27A has occurred thus rendering the signal CCA1 inadequate to control these gates. As the circuit EC1 is triggered by ROGP it is in its non-conducting condition from addition period 2 until the beginning of the check calculation when it is reset by the master reset MR and so is adequate to cover the over-capacity occurring just after the calculation stop signal has been given. Should both sides of a gate MDCG, NDCG, ODCG be conditioned, indicating the detection of an over-capacity condition, a signal will pass through cathode follower CF12 and amplifier AMP and will be stored or memorised by circuit EC2 until switch ETS opens

when it will pass to relay OCR which, being energised, closes the circuit to the reset solenoid RS, Fig. 19, thus effecting resetting of punches and insuring that no result is punched in the card.

- 5 Gates PDCG and QDCG are each connected at one side to a transmit gate TG and at the other side receive pulse CCA1, Fig. 27A, but a signal from the output point of either of these gates to EC2 is controlled by the pulses MPS1A0 and MPS2A0 so that it is only while these pulses are operative, that is during the periods stated above for condition 2, that a signal indicating a condition of over-capacity can pass to EC2 to energise OCR on opening of switch ETS.

Gate RDCG is connected at one side to output DPS5 and at the other side to a contact A01 of a normally closed relay A0, and to contact B01 of a normally closed relay B0. Should a sensing switch MCS be closed as the result of the sensing, the £10⁰ of £10¹, or £10² card columns both sides of gate RDCG will be conditioned and a signal will pass from the output point of the gate to MIX so that on opening of ETS it will energise relay OCR.

Gate SDCG is connected at one side to the output DPSO, Fig. 3B, which is operative, should a perforation be sensed in the 10³ multiplier column of the card, and at the other side to a contact B01 of a relay B0. Should a sensing switch MCS be closed as the result of the sensing of the £10² card column both sides of gate SDCG will be conditioned and a signal will pass from the output point of the gate to MIX so that on opening of ETS it will energise relay OCR.

Referring to Fig. 19 it will be noted that the circuit to relay OCR includes a switch OCS which is a manually operable switch. Switch OCS can be operated when it is not desired to detect over-capacities and when so operated, provided that the multiplicand contains no decimal fractions of pence and the multiplier is a whole number, the maximum capacity of the register CR2 can be increased to £999,999-19-11d. by employing the 10⁻² counter to register £10⁴ and the 10⁻¹ counter to register £10⁵.

40 The foregoing describes the apparatus according to the invention and the manner in which the apparatus operates and there now follows a brief description of the manner in which the appropriate impulses are provided and passed to the apparatus.

45 Referring to Figs. 2A, 2B and 15, there is provided a normally open cam operated start control switch SCS, Fig. 15, and also a normally open cam operated start switch SS.

The switch SCS ensures that the apparatus is properly 50 conditioned prior to the operation of start switch SS on the application of a programme trigger pulse PPT. On closing of the start switch SS, a pulse passes to a pre-start gate PSG, Fig. 2A, and thence to a start control device SC comprising an Eccles-Jordan trigger circuit, stopping of 55 the operation being effected by a stop pulse entering SC at the appropriate time. The output from the start control SC passes through a cathode follower CF14 to a start gate SG, Fig. 2B, to which is also fed a pulse PPT. The first PPT pulse to be gated by the start gate SG, when 60 conditioned by the start switch SS opening, triggers the trigger circuit MR via amplifier AMP on the leading edge of the pulse. This trigger circuit is reset by the back edge of one of the PPT pulses continuously applied to MR. The output RRR from the trigger MR serves as the 65 master reset pulse for registers R, CR1 and CR2, and also triggers the trigger circuit MGC on the back edge of the pulse. When MGC is thus triggered it closes gate SG so that no further output of gated PPT pulses occurs to trigger MR again until after a stop pulse has reset MGC and 70 the start switch SS has re-opened.

Pulses from a multivibrator MU, Fig. 2B, having a frequency of 20 kilo-cycles are fed to an Eccles-Jordan trigger circuit HA which halves the frequency of the pulses. Pulses from HA are passed to the master gate MG which 75 is controlled by the output MGP from MGC through

cathode follower CF15. The output pulses from master gate MG are cycling pulses CYP, Fig. 25A, fed along line DCP, Fig. 2B, to cycling unit gates CUG and to the programme control pulse gate PCPG, Fig. 2A, to initiate operation of the programme unit and the calculation begins. At the end of the calculation the programme unit returns a stop pulse, referred to below, to the master gate control MGC, and the start control SC, along line SPL, Figs. 2A and 2B, closing the master gate MG which remains closed until the start switch SS is again closed.

The cycling unit counter CUC comprises four Eccles-Jordan trigger circuits indicated in Fig. 2B as S1, S2, S3 and S4, these being the four stages of the counter, triggered by the output from the halver HA. Pulses from the cycling unit counter pass through cathode followers CF16 to cycling unit gates CUG from which pulses are passed to the cycling selector MR CSG, Figs. 2A and 10, to master reset gates, start gate SG, start switch SS and to programme control pulse gates PCPG, Figs. 2 and 26, and thence to multiplicand add control unit MAC, Figs. 2A and 26.

Figs. 24 and 24B is a wave form diagram of the cycling unit counter CUC and Figs. 25A and 25B illustrates the manner in which the cycling unit coincidence gates CUG controls the outputs from the cycling unit counter.

From Figs. 24 and 24B will be seen the manner in which the input pulses from HA are distributed through CUC and the wave forms for the various outputs from CUC are also illustrated. The outputs which are obtained from the cycling unit counter are a pulse CPP which is fed to the programme unit gates PUG to issue therefrom as a complement pulse CP, the digit registering pulses DP1, DP2, DP4, DP2* and DP4*, which are passed to the cycling selector gates CSG, Fig. 10 as described above, the PPT pulse, the register reset pulse RR, and a register set pulse RSP, these last two pulses being fed to the programme unit gates PUG. The register set pulse RSP also also acts as a carry reset pulse CR, Figs. 24A and 25B. Also shown in Fig. 24A is a wave form COP which is the wave form for the carry-over pulse to effect carries in the registers CR1 and CR2, but this pulse is not generated by the unit CUC but by an Eccles-Jordan trigger circuit EC3 (Fig. 2B).

In Fig. 24A the wave forms for unit CUC are tagged by the references S1, S2, S3, S4, and an indication of the anodes for each stage is also given by the references A0, A1 suffixed thereto. At the right of Fig. 24B is shown the coincidences by which the various pulses are generated and this is more clearly illustrated in Figs. 25A and 25B from which it will be seen that the pulses each pass from the gates CUG through a cathode follower CP17.

The programme unit is under control of the programme control pulse gate PCPG and comprises the multiplicand add control unit MAC, Figs. 2A and 26, a multiplier control pulse gate MCGP, a multiplier control counter MC, Fig. 2B, a multiplier control counter gate MCG, Fig. 26 a multiplication programme unit MP, Fig. 2B, and a calculation check control unit CC which consists of an Eccles-Jordan trigger circuit.

The programme unit is diagrammatically illustrated in Fig. 26, from which it will be seen that the programme control pulse gate PCPG consists of a diode coincidence gate the output of which is connected to MAC which consists of two Eccles-Jordan trigger circuits indicated at S1 and S2. The output from MAC passes to the multiplier control pulse gate MCGP which consists of a further diode coincidence gate, the output from which passes to the multiplier control counter MC. The multiplier control counter MC consists of three Eccles-Jordan trigger circuits indicated as S1, S2, and S3 respectively and a coincidence gate MCG as shown in Fig. 26 and the unit MC is connected with the multiplication programme unit MP which latter unit also consists of two Eccles-Jordan trigger circuits, indicated in Fig. 26 as S1 and S3 respectively. The unit MP, as can be seen from Fig. 2B,

is connected with the calculation check control unit CC which comprises an Eccles-Jordan trigger circuit.

The programme unit is triggered by the pulse PPT, that is it changes its state each addition period. The multiplicand add control unit MAC is concerned with addition periods 1 and 2 and the multiplier control counter MC is a scale-of-five counter concerned with the multiplier control pulses MC1, MC2, MC4, MC2* starting its count at addition period 3 and repeating itself every five addition periods. The multiplication programme unit MP is a scale-of-four counter triggered by the multiplier control counter MC and counts multiplication periods MP1, MP2, MP3, MP4; when it has counted the four periods its output serves as a stop pulse as it occurs after addition period 22, that is after twenty-two pulses PPT. Stop pulses also trigger the check control counter CC, which, consequently, is in one condition for the calculation and another for the check calculation. The wave forms for these various pulses are shown on Figs. 25A and 25B.

From Figs. 28A, 28B and 28C it will be seen that the outputs from the trigger circuits MAC, MC, MP and CC are taken to the programme unit gates PUG, which gates are of the coincidence type, where they are coincided with each other and with inputs from the cycling unit gates CUG to obtain the required output pulses at the required times during the calculation and check calculation operations. These output pulses and their timing are shown in the wave form diagram Figs. 27A and 27B together with notes indicating the coincidences by which they are produced.

From Figs. 27A, 27B, 28A, 28B and 28C it will be observed that on leaving the programme unit gates PUG the pence set pulses PSP, the shillings set pulses SSP, and the pulses MCS each pass through a cathode follower CF18, an inverter INV, Figs. 28A and 28B, and thence through a cathode follower CF19.

We claim:

1. In an electrical calculating machine controlled by statistical record cards, calculating apparatus comprising a non-counting register, a first counting register, a second counting register to act as a result register, each said register including a plurality of denominational orders each including at least one binary counter by which a digit is registered, transfer gates connected to said non-counting and first counting registers to control the entry into the non-counting register of an amount stored in the first counting register, cycling selector gates connecting the non-counting and first counting register to control the entry of a amount stored in the non-counting register to the first counting register, transmit gates connecting the cycling selector gates and second counting register to control the entry of an amount stored in the non-counting register to the second counting register, and programme unit gates to control sequential operation of the transfer gates and selective operation of the transmit gates, recording means to record the result registered in the second counting register, and read-out means co-operating with the second counting register to transmit digit-representing pulses to the recording means to set up therein a record of the result read-out from the second counting register.

2. Apparatus according to claim 1, wherein a sequence of operations of the transfer gates consists of a succession of groups of addition periods each group consisting of five addition periods and a group being provided for each denomination of a multiplier of predetermined magnitude, and wherein the programme unit gates control reset pulses to reset the non-counting register between the fifth and first and between the first and second addition periods of each said group whereby subsequent to the entry of a multiplicand into the first counting register the multiplicand is multiplied in the first counting register by said predetermined multiplier by, during each group of addition periods, in the first period of a group transferring to the non-counting register the amount stored in the first

counting register immediately prior to said first period and cycling the amount so registered to the first counting register to double the amount stored therein, in the second period of the group transferring to the non-counting register said doubled amount stored in the first counting register and cycling the amount so registered to the first counting register, and during each of the third, fourth and fifth periods of the group cycling the amount last registered in the non-counting register to the first counting register.

3. Apparatus according to claim 2, wherein pulse gates connected with said programme unit gates and non-counting register are operative on receipt of set pulses to control the entry of a multiplicand into the non-counting register to be cycled therefrom to the first counting register.

4. Apparatus according to claim 3, wherein to enter a Sterling multiplicand into the first counting register two successive set pulses are applied to the pulse gates each to enter a part of the multiplicand into the non-counting register to be cycled to the first counting register, a reset pulse being applied to the non-counting register between the application of said two set pulses.

5. Apparatus according to claim 4, including a static network of coincidence gates to receive multiplicand numbers sensed from a record card and to convert the sensed numbers into a predetermined code, a decimal point selector to determine the number of significant digits to the left of the decimal point if there are digits to the right of a multiplier sensed from the card and to control said network so that the multiplicand issues therefrom in code and divided by a power of ten as determined by the decimal point selector.

6. Apparatus according to claim 5, wherein division of a number is effected by a diode coincidence gate connected to a pulse gate, said diode coincidence gate being connected to said decimal point selector.

7. Apparatus according to claim 5, including a static network of coincidence gates to receive multiplier digits sensed from the card and to convert them according to a predetermined code, said network being controlled by said decimal point selector so that the sensed multiplier issues therefrom multiplied by a power of ten as determined by the decimal point selector.

8. Apparatus according to claim 6, including a static network of coincidence gates to receive multiplier digits sensed from the card and to convert them according to a predetermined code, said network being controlled by said decimal point selector so that the sensed multiplier issues therefrom multiplied by a power of ten as determined by the decimal point selector.

9. Apparatus according to claim 8, wherein the decimal point selector includes for each column of a card field to be sensed, electrical switch means actuated by the sensing of a significant digit recorded in the card column appropriate thereto, electrical connections connecting one switch means with another, an electrical transfer line common to all said switch means, an input line connected to the switch means of lowest denomination, and an output line from each switch means representative of positive powers of ten, said electrical connections being such that a pulse along the input line is transferred to the transfer line by the first encountered actuated switch means representative of a negative power of ten and is directed thereby to switch means representative of the highest positive power of ten to pass a signal from the output line of the first encountered actuated switch means representative of a positive power of ten.

10. Apparatus according to claim 9, wherein the input line is connected through the switch means representative of the negative powers of ten to the output line from the switch means representative of the highest power of ten when no switch means representative of a negative power of ten is actuated.

11. Apparatus according to claim 9, wherein each

switch means consist of a relay and two switches operable simultaneously by the relay, one switch for each relay being electrically connected to said input line and to an output line along which if the switch is not actuated to indicate the sensing of a significant digit in the card column appropriate thereto said pulse passes to give a zero indication.

12. Apparatus according to claim 10, wherein each switch means consists of a relay and two switches operable simultaneously by the relay, one switch for each relay being electrically connected to said input line and to an output line along which if the switch is not actuated to indicate the sensing of a significant digit in the card column appropriate thereto said pulse passes to give a zero indication.

13. Apparatus according to claim 12, including a multivibrator to initiate pulses to control the apparatus, a trigger circuit connected to the multivibrator to halve the frequency of pulses initiated thereby, a cycling unit connected to said trigger circuit and including a four-stage divider of which each stage consists of a trigger circuit, said divider operating to generate a succession of pulses in groups of sixteen pulses each, and cycling unit gates to direct the pulses of each group to the parts of the apparatus to be operated thereby.

14. In an electrical calculating machine controlled by statistical record cards, calculating apparatus for effecting multiplication comprising a non-counting register, a first counting register, a second counting register to act as a result register, each said register including a plurality of denominational orders each including at least one binary counter by which a digit is registered, transfer gates connected to said non-counting and first counting registers to control the entry into the non-counting register of an amount stored in the first counting register, cycling selector gates connecting the non-counting and first counting registers to control the entry of an amount stored in the non-counting register to the first counting register, transmit gates connecting the cycling selector gates and second counting register to control the entry of an amount stored in the non-counting register to the second counting register, programme unit gates to control sequential operation of the transfer gates and selective operation of the transmit gates, pulse gates connected with the programme unit gates and non-counting register to control the entry of a multiplicand in the non-counting register to be cycled therefrom to the first counting register, recording means to record the result registered in the second counting register, read-out means co-operating with the second counting register to transmit digit-representing pulses to the recording means to set up therein a record of the result read-out from the second counting register, reset means operative on conclusion of a multiplication operation to reset the non-counting and first counting registers preparatory to the multiplicand being re-entered into the first counting register, complement pulse means operative in succession to the read-out means and subsequent to the re-entry of the multiplicand into the first counting register to set up in the first counting register the complement of the multiplicand preparatory to the complement of the multiplicand being multiplied by the multiplier to effect checking of the result stored in the second counting register, means to enter a unit digit into the second counting register to accommodate the "fugitive one," and error trip means operable to effect cancellation of the set-up of the recording means in the event that a significant digit is registered in the second counting register on termination of the checking operation.

15. Apparatus according to claim 14, wherein the unit digit entering means is operative during operation of the complement pulse means.

16. Apparatus according to claim 15, wherein the second counting register includes denominational orders representative of digit values 10^{-1} and 10^{-2} such orders being excluded from the checking operation.

17. Apparatus according to claim 16 wherein the unit digit is entered into the denominational order of the second counting register representative of digit values 10^{-2} .

18. Apparatus according to claim 17, including over-capacity detector means co-operating with the second counting register and recording means to effect operation of said error trip means when entries to the second counting register exceed the capacity thereof.

19. Apparatus according to claim 18, including a static network of coincidence gates to receive multiplicand numbers sensed from a record card and to convert the sensed numbers into a predetermined code, a decimal point selector to determine the number of significant digits to the left of the decimal point if there are digits to the right of a multiplier sensed from the card and to control said network so that the multiplicand issues therefrom in code and divided by a power of ten as determined by the decimal point selector.

20. Apparatus according to claim 19, wherein division of a number is effected by a diode coincidence gate connected to a pulse gate, said diode coincidence gate being connected to said decimal point selector.

21. Apparatus according to claim 20, wherein the over-capacity detector means includes a first diode co-incidence gate in the carry circuit for a denominational order of the second counting register, a second diode coincidence gate connected to said first gate and controlled by said decimal point selector and an Eccles-Jordan trigger circuit which is non-conducting during a calculation and conducting during a checking operation, a cam-operated error trip switch to condition said error trip means for operation, and an over-capacity memory conditioned by said first gate to permit operation of the error trip means on conditioning thereof by said trip switch.

22. Apparatus according to claim 21, wherein a sequence of operations of the transfer gates consists of a succession of groups of addition periods each group consisting of five addition periods and a group being provided for each denomination of a multiplier of predetermined magnitude, and wherein the programme unit gates control reset pulses to reset the non-counting register between the fifth and first and between the first and second addition periods of each said group whereby subsequent to the entry of a multiplicand into the first counting register the multiplicand is multiplied in the first counting register by said predetermined multiplier by, during each group of addition periods, in the first period of a group transferring to the non-counting register the amount stored in the first counting register immediately prior to said first period and cycling the amount so registered to the first counting register to double the amount stored therein, in the second period of the group transferring to the non-counting register said doubled amount stored in the first counting register and cycling the amount so registered to the first counting register, and during each of the third, fourth and fifth periods of the group cycling the amount last registered in the non-counting register to the first counting register.

23. Apparatus according to claim 22, wherein pulse gates connected with said programme unit gates and non-counting register are operative on receipt of set pulses to control the entry of a multiplicand into the non-counting register to be cycled therefrom to the first counting register.

24. Apparatus according to claim 23, wherein to enter a Sterling multiplicand into the first counting register two successive set pulses are applied to the pulse gates each to enter a part of the multiplicand into the non-counting register to be cycled to the first counting register, a reset pulse being applied to the non-counting register between the application of said two set pulses.

25. Apparatus according to claim 24 including a static network of coincidence gates to receive multiplier digits sensed from the card and to convert them according to a predetermined code, said network being controlled by said decimal point selector so that the sensed multiplier

issues therefrom multiplied by a power of ten as determined by the decimal point selector.

26. Apparatus according to claim 25, wherein the decimal point selector includes for each column of a card field to be sensed, electrical switch means actuated by the sensing of a significant digit recorded in the card column appropriate thereto, electrical connections connecting one switch means with another, an electrical transfer line common to all said switch means, an input line connected to the switch means of lowest denomination, and an output line from each switch means representative of positive powers of ten, said electrical connections being such that a pulse along the input line is transferred to the transfer line by the first encountered actuated switch means representative of a negative power of ten and is directed thereby to the switch means representative of the highest positive power of ten to pass a signal from the output line of the first encountered actuated switch means representative of a positive power of ten.

27. Apparatus according to claim 26, wherein the input line is connected through the switch means representative of the negative powers of ten to the output line from the switch means representative of a negative power of ten when no switch means representative of a negative power of ten is actuated.

28. Apparatus according to claim 27, wherein each switch means consists of a relay and two switches operable simultaneously by the relay, one switch for each relay being electrically connected to said input line and to an output line along which if the switch is not actuated to indicate the sensing of a significant digit in the card column appropriate thereto said pulse passes to give a zero indication.

29. In an electrical calculating machine controlled by statistical record cards, calculating apparatus for effecting multiplication of Sterling amounts comprising a non-counting register, a first counting register, a second counting register to act as a result register, each said register including a plurality of denominational orders each including at least one binary counter by which a digit is registered and each including denominational orders representative of values 10^{-1} and 10^{-2} , transfer gates connected to said non-counting and first counting registers to control the entry of an amount stored in the first counting register to the non-counting register, cycling selector gates connecting the non-counting and first counting registers to control the entry of an amount stored in the non-counting register to the first counting register, transmit gates connecting the cycling selector gates and second counting register to control the entry of an amount stored in the non-counting register to the second counting register, programme unit gates to control sequential operation of the transfer gates and selective operation of the transmit gates, pulse gates connected with the programme unit gates and non-counting register to control the entry in two stages of a multiplicand in the non-counting register to be cycled therefrom to the first counting register, reset means to apply a reset pulse to the non-counting register between the entry thereinto of said two stages, recording means to record the result registered in the second counting register, read-out means co-operating with the second counting register to transmit digit-representing pulses to the recording means to set up therein a record of the result read out from the second counting register, and a manually selective device operative to effect entry into at least one of the denominational orders of the second counting register representative of digit values 10^{-1} and 10^{-2} of a predetermined digit to effect rounding-off of the result to the nearest penny or to the nearest farthing.

30. Apparatus according to claim 29, wherein a sequence of operations of the transfer gates consists of a succession of groups of addition periods each group consisting of five addition periods and a group being provided

for each denomination of a multiplier of predetermined magnitude, and wherein the programme unit gates control reset pulses to reset the non-counting register between the fifth and first and between the first and second addition periods of each said group whereby subsequent to the entry of a multiplicand into the first counting register the multiplicand is multiplied in the first counting register by said predetermined multiplier by, during each group of addition periods, in the first period of a group transferring to the non-counting register the amount stored in the first counting register immediately prior to said first period and cycling the amount so registered to the first counting register to double the amount stored therein, in the second period of the group transferring to the non-counting register said doubled amount stored in the first counting register and cycling the amount so registered to the first counting register, and during each of the third, fourth and fifth periods of the group cycling the amount last registered in the non-counting register to the first counting register.

31. Apparatus according to claim 30, wherein pulse gates connected with said programme unit gates and non-counting register are operative on receipt of set pulses to control the entry of a multiplicand into the non-counting register to be cycled therefrom to the first counting register.

32. Apparatus according to claim 31, including a static network of coincidence gates to receive multiplicand numbers sensed from a record card and to convert the sensed numbers into a predetermined code, a decimal point selector to determine the number of significant digits to the left of the decimal point if there are digits to the right of a multiplier sensed from the card and to control said network so that the multiplicand issues therefrom in code and divided by a power of ten as determined by the decimal point selector.

33. Apparatus according to claim 32, wherein division of a number is effected by a diode coincidence gate connected to a pulse gate, said diode coincidence gate being connected to said decimal point selector.

34. Apparatus according to claim 33, including a static network of coincidence gates to receive multiplier digits sensed from the card and to convert them according to a predetermined code, said network being controlled by said decimal point selector so that the sensed multiplier issues therefrom multiplied by a power of ten as determined by the decimal point selector.

35. Apparatus according to claim 34, wherein the decimal point selector includes for each column of a card field to be sensed, electrical switch means actuated by the sensing of a significant digit recorded in the card column appropriate thereto, electrical connections connecting one switch means with another, an electrical transfer line common to all said switch means, an input line connected to the switch means of lowest denomination, and an output line from each switch means representative of positive powers of ten, said electrical connections being such that a pulse along the input line is transferred to the transfer line by the first encountered actuated switch means representative of a negative power of ten and is directed thereby to the switch means representative of the highest positive power of ten to pass a signal from the output line of the first encountered actuated switch means representative of a positive power of ten.

36. Apparatus according to claim 35, wherein the input line is connected through the switch means representative of the negative powers of ten to the output line from the switch means representative of the highest power of ten when no switch means representative of a negative power of ten is actuated.

37. Apparatus according to claim 36, wherein each switch means consists of a relay and two switches operable simultaneously by the relay, one switch for each relay being electrically connected to said input line and

to an output line along which if the switch is not actuated to indicate the sensing of a significant digit in the card column appropriate thereto said pulse passes to give a zero indication.

5 38. Apparatus according to claim 37 including reset means operative on conclusion of a multiplication operation to reset the non-counting and first counting registers preparatory to the multiplicand being re-entered into the first counting register, complement pulse means 10 operative in succession to the read-out means and subsequent to the re-entry of the multiplicand into the first counting register to set up in the first counting register the complement of the multiplicand preparatory to the complement of the multiplicand being multiplied by the 15 multiplier to effect checking of the result stored in the second counting register, means to enter a unit digit into the second counting register to accommodate the "fugitive one," and error trip means operable to effect cancellation of the set-up of the recording means in the 20 event that a significant digit is registered in the second counting register on termination of the checking operation.

39. Apparatus according to claim 38, wherein the unit digit entering means is operative during operation of 25 the complement pulse means.

40. Apparatus according to claim 39, wherein the second counting register includes denominational orders representative of digit values 10^{-1} and 10^{-2} such orders being excluded from the checking operation.

30 41. Apparatus according to claim 40, wherein the unit digit is entered into the denominational order of the second counting register representative of digit values 10^{-2} .

42. In an electrical multiplying machine controlled by 35 statistical record cards, apparatus comprising a non-counting register, a first counting register, a second counting register to act as a result register, each said register including a plurality of denominational orders each including at least one binary trigger circuit by which a digit is registered, converter means to convert a multiplier containing a fraction to a whole number and simultaneously to divide a multiplicand by the amount employed to convert the multiplier to said whole number, means to enter the divided multiplicand into said non-counting register, cycling selector gates connecting the non-counting and first counting registers to control the entry of an amount stored in the non-counting register to the first counting register, transmit gates connected to the non-counting and first counting registers to control the entry into the non-counting register of an amount stored in the first counting register, transmit gates connecting the cycling selector gates and second counting register to control the entry of an amount stored in the non-counting register to the second counting register, and programme unit gates to control sequential operation of the transfer gates and selective operation of the transmit gates.

43. Apparatus according to claim 42, wherein the converter means includes a static network of coincidence gates to receive multiplicand numbers sensed from a record card and to convert the sensed numbers into a predetermined code, a decimal point selector to determine the number of significant digits to the left of the decimal point if there are digits to the right of a multiplier sensed from the card and to control said network so that the multiplicand issues therefrom in code and divided 50 by a power of ten as determined by the decimal point selector.

44. Apparatus according to claim 43, wherein division of a number is effected by a diode coincidence gate connected to a pulse gate, said diode coincidence gate being connected to said decimal point selector.

45. Apparatus according to claim 44, including a static network of coincidence gates to receive multiplier digits sensed from the card and to convert them according to 75 a predetermined code, said network being controlled by

said decimal point selector so that the sensed multiplier issues therefrom multiplied by a power of ten as determined by the decimal point selector.

46. Apparatus according to claim 45, including a static network of coincidence gates to receive multiplier digits sensed from the card and to convert them according to a predetermined code, said network being controlled by said decimal point selector so that the sensed multiplier issues therefrom multiplied by a power of ten as determined by the decimal point selector.

47. Apparatus according to claim 46, wherein pulse gates connected with said programme unit gates and non-counting register are operative on receipt of set pulses to control the entry of a multiplicand into the non-counting register to be cycled therefrom to the first counting register.

48. In an electrical multiplying machine controlled by statistical record cards, apparatus comprising a non-counting register, a first counting register, a second counting register to act as a result register, each said register including a plurality of denominational orders each including at least one binary trigger circuit by which a digit is registered, transfer gates connected to said non-counting register and first counting register and operative sequentially to permit the passage of a group of addition pulses for each denomination of a multiplier of predetermined magnitude, each group consisting of a predetermined number of addition pulses, to control the entry into the non-counting register of an amount stored in the first counting register, cycling selector gates connecting the non-counting register and the first counting register to control the entry of an amount stored in the non-counting register to the first counting register during each addition pulse whereby at the end of a group of addition pulses the first counting register stores a value which is a predetermined multiple of the amount registered in the non-counting register at the end of the first addition pulse of the group, transmit gates connecting the cycling selector gates and second counting register to control the entry of an amount stored in the non-counting register to the second counting register, and programme unit gates selectively to control operation of the transmit gates according to the value of denominational multiplier digits, to control sequential operation of the transmit gates, and to transmit reset pulses to the non-counting register between the last pulse of one group and the first pulse of the next group and between the first and second pulses of each group.

49. Apparatus according to claim 48, wherein pulse gates connected with said programme unit gates and non-

counting register are operative on receipt of set pulses to control the entry of a multiplicand into the non-counting register to be cycled therefrom to the first counting register.

50. Apparatus according to claim 49, wherein to enter a Sterling multiplicand into the first counting register two successive set pulses are applied to the pulse gates each to enter a part of the multiplicand into the non-counting register to be cycled to the first counting register, a reset pulse being applied to the non-counting register between the application of said two set pulses.

51. Apparatus according to claim 48, including recording means to record the result registered in the second counting register, read-out means co-operating with the second counting register to transmit digit-representing pulses to the recording means to set up therein a record of the result read-out from the second counting register, reset means operative on conclusion of a multiplication operation to reset the non-counting and first counting registers preparatory to the multiplicand being re-entered into the first counting register, complement pulse means operative in succession to the read-out means subsequent to the re-entry of the multiplicand into the first counting register to set up in the first counting register the complement of the multiplicand preparatory to the complement of the multiplicand being multiplied by the multiplier to effect checking of the result stored in the second counting register, means to enter a unit digit into the second counting register to accommodate the "fugitive one," and error trip means operable to effect cancellation of the set up of the recording means in the event that a significant digit is registered in the second counting register on termination of the checking operation.

52. Apparatus according to claim 51, wherein the unit digit entering means is operative during operation of the complement pulse means.

53. Apparatus according to claim 52, wherein the second counting register includes denominational orders representative of digit values 10^{-1} and 10^{-2} such orders being excluded from the checking operation.

54. Apparatus according to claim 53, wherein the unit digit is entered into the denominational order of the second counting register representative of digit values 10^{-2} .
